This invention relates to a calculating machine, and particularly to an improved multiplying mechanism which, in a preferred embodiment, provides means particularly adapted to square a value set in the selection mechanism, i.e., to multiply such a factor by itself, either additively or subtractively, this application being a continuation-in-part of my copending application, S.N. 419,402, filed March 29, 1954, now abandoned.

A primary object of the present invention is to provide a simple multiplying mechanism, and, for purposes of illustration, is shown as cooperating with a calculating machine of the type disclosed by the patent to Friden, No. 2,229,889, issued January 28, 1941. However, it will be recognized by those familiar with the art, that the mechanism of the present invention could be included readily in other types of calculating machines. The multiplying mechanism of the present invention can either be in addition to, or in substitution for, multiplying mechanisms of the types shown in the patents to Friden Nos. 2,371,752 of March 20, 1945 and 2,399,917 of May 7, 1946. For purposes of illustration, the present invention is shown in addition to these prior mechanisms, although it will be recognized that the mechanisms of these last-mentioned patents may be eliminated and the present in-

vention utilized as the sole multiplying mechanism of the calculating machine.

Another primary object of the present invention is to provide a calculating machine in which a multiplier factor is set in the main keyboard of the machine and thence into a multiplier storage unit (the multiplicand also being set in the same keyboard), thus providing a simple means for multiplying a value set in the main keyboard by itself, whereby a value may be squared by inserting the value once in the main keyboard and thereafter operating a control key.

Another object of the present invention is to provide a multiplying control mechanism which may be supplemental to a conventional multiplying mechanism, such as that disclosed in the patents to Friden Nos. 2,371,752 and 2,399,917, and which may be operated to utilize either a factor set in the main keyboard or a value transferred from some register, such as the accumulator (product) register, thereby using either a main keyboard value or an accumulated value as a multiplier factor and which may utilize conventional multiplier control keys to selectively determine the type of operation to be performed.

Another object of the present invention is to provide a multiplying mechanism which utilizes parts already available in the "Friden" calculating machine for extracting a square root, such as is described in my Patent No. 2,736,494 of myself and another, issued February 28, 1956.

Another object of the present invention is to combine a multiplying mechanism with a machine for the extraction of square root of the type described in my joint Patent No. 2,736,494 whereby the mechanism of the present invention not only may be combined with a machine for extracting square root, but will use much of the mechanism of the square root machine and thereby save considerable space and many parts.

A secondary object of the present invention is to provide a calculating machine capable of multiplying a value set in the main keyboard, or selection mechanism, by itself, whereby a value may be squared by inserting the value once into the main keyboard and thereafter operating a control key. In this respect, the mechanism of the present invention may use a multiplier register into which the keyboard value may be set as an intermediate step, or may omit the multiplier register and directly use the keyboard factor as the multiplier, as well as the multiplicand, as will be explained in the second embodiment to be described herein.

The present invention has the further advantage that I am enabled to utilize the multiplier control keys conventional in the machine of the Friden patents previously mentioned: (a) to clear the register with each problem, (b) to operate without clearing the register and thereby add one product to another in the accumulator, or (c) to "negatively multiply" the factor set in the multiplier storage (to thereby subtract a product or a square from values already registered in the accumulator).

The mechanism of my invention may be coupled with the conventional multiplier mechanism of the Friden patents above-mentioned, so that the operator can use the conventional multiplier for ordinary multiplication operations, or can use the mechanism of my invention either to square a value set in the keyboard or to use a value accumulated in the conventional accumulator as a multiplier factor.

A further object of the present invention is to provide an improved mechanism by means of which a value set in the main keyboard of a calculating machine may be quickly and accurately used as a multiplier factor when and as desired, either once or repeatedly.

These and other objects of my invention will be apparent from the description and claims which follow.

For purposes of disclosure, the invention will be shown and described as embodied in a square root machine of the type disclosed in my joint patent above-mentioned, which, in turn, is embodied in a machine of the type disclosed in the three patents to Carl M. Friden above-mentioned. It will be understood, however, that the invention is not limited to incorporation in such a machine for it can be incorporated in, or applied to, other commercial calculating machines on the market, and does not need to be associated with a mechanism for the extraction of square root. Therefore, the machine shown in the accompanying drawings and described herein is to be considered as a preferred embodiment, used only for the purpose of exemplification, for the invention is not limited to the machine so shown.

Parts of the mechanism disclosed in the above patents which are associated with the mechanism of this invention, are disclosed herein in order to show the environment of the novel structure of the present invention. It will be understood that in these views many mechanisms and parts not associated with the mechanism of my invention, are eliminated for simplification—only those parts being retained which cooperate with the novel mechanism of my machine. Such conventional mechanisms will be described as briefly as possible and yet explain the novel mechanism of my invention and to illustrate its operation. For a full disclosure of any of these mechanisms shown and herein briefly described, or for related mechanisms not shown or described, reference is made to the afore-mentioned patents, or others which may be mentioned hereafter.

It is believed that the invention will be more readily understood by a reference to the drawings which form a part of this specification, and in which:

FIG. 1 is a plan view of a preferred form of a machine with which my invention can be associated.

FIG. 2 is a cross-sectional view through one order of the actuating mechanism and register of the machine shown in FIG. 1.

FIG. 3 is a left side view of the right-hand control plate, with certain mechanisms pertinent to my invention shown thereon.

FIG. 4 is a plan view of the shifting and clearing mechanisms conventional in the machine shown in FIG. 1.

FIG. 5 is a rear view of the machine shown in FIG. 1.

FIG. 6 is a longitudinal cross-sectional view of the multiplier selection and operating mechanism, such as taken along the longitudinal vertical plane indicated by the line 6—6 of FIG. 1.

FIG. 7 is a longitudinal cross-sectional view of a portion of the multiplier control mechanism, such as taken along the longitudinal vertical plane indicated by the line 7—7 of FIG. 1.

FIG. 8 is a detail of one of the conventional operating mechanisms of the machine with which my invention is associated.

FIG. 9 is a cross-sectional view looking toward the right and taken immediately to the right, or inside, of the left side control plate, as along the longitudinal vertical plane indicated by the line 9—9 of FIG. 1, and shows a portion of the multiplication control mechanisms.

FIG. 10 is a left side view of the left side control plate, being taken immediately to the left of the plane indicated by line 9—9, showing additional mechanisms associated with the multiplier mechanism.

FIG. 11 is a left side view taken from substantially the same plane as FIG. 10, but showing thereon the mechanisms of the present invention, and in effect, can be considered as superimposed over FIG. 10 to show the relationship between the conventional and new mechanisms.

FIG. 12 is a plan view, on an enlarged scale, of mechanisms associated with my invention, and, in effect, is taken along the plane parallel to the keyboard indicated by the line 12—12 of FIGS. 9 and 11.

FIG. 13 is a longitudinal cross-sectional view through the multiplying feed mechanism of my invention, and

shows particularly the similarity of the mechanism of the present invention to the square root mechanism of my joint patent, above-mentioned, as will be obvious by reference to FIG. 42 of that patent.

FIG. 14 is a detail, an enlarged scale, of the feed mechanism for the cam, or ordinal selection, shaft.

FIG. 15 is a front view of the multiplying (and square root) control assembly of my invention.

FIG. 16 is a cross-sectional view, taken on a longitudinal vertical plane, of the multiplier storage mechanism and the means for controlling a multiplication operation therefrom.

FIG. 17 is a left side view, on a somewhat enlarged scale, of control mechanisms associated with my invention, taken on a vertical longitudinal plane intermediate the left-hand auxiliary and frame plates, as along the plane indicated by the line 17—17 of FIG. 1.

FIG. 18 is a detail of the keyboard clearing mechanism, being a view taken of the left side of the right side frame plate.

FIG. 19 is a front view of certain mechanisms shown in part in FIG. 18, relating particularly to the clearing of the multiplication mechanism.

FIG. 20 is a side view of the conventional selection bars and the auxiliary, or feed, slide of the second embodiment of my invention, with the parts in the "0" position.

FIG. 21 is a view similar to FIG. 20 but showing the relationship of the parts when a value of "5" has been entered by the auxiliary, or feed, slide.

FIG. 22 is a left side view of the "1" to "5" selection bar with the interponent member mounted thereon.

FIG. 23 is a detail plan view of the parts shown in FIGS. 20 and 21.

FIG. 24 is a partial plan view of the mechanism associated with the second embodiment of my invention for locking the selection slides registering a "0" value in their "0" position.

FIG. 25 is a front view of the mechanism shown in FIG. 24.

FIG. 26 is a cross-sectional view through the "0" blocking mechanism of FIGS. 24 and 25, such as taken along the plane indicated by line 26—26 of FIG. 25.

I. GENERAL DESCRIPTION

The present invention, in its preferred form, is an improvement on a calculating machine of the type disclosed in the above-mentioned Patent No. 2,229,889, issued to Carl M. Friden on January 28, 1941. The invention is shown, for purposes of exemplification, as combined with the multiplier mechanism shown in the patents to Carl M. Friden, Nos. 2,371,752 and 2,399,917 issued on March 20, 1945 and May 7, 1946, respectively. The present invention is also shown as being applied to the machine for the extraction of square root shown and described in my joint Patent No. 2,736,494, issued February 28, 1956, above-mentioned, as I prefer that the mechanism of the present invention utilizes many of the parts shown in that patent. It will be understood, however, that the multiplying mechanism of the present invention and the square root extraction mechanism of my said patent, are not necessarily associated one with the other for, although many of the same parts are used, the two mechanisms operate separately and do not necessarily have to be associated with the mechanism of the other. Neither is it necessary that the multiplying mechanisms of the Friden patents be combined with the present mechanism, for the present invention, *per se*, constitutes an improved multiplying mechanism.

The complete machine with which my invention is preferably associated is shown in FIG. 1. The machine comprises a body portion 50 containing the actuating, selecting and control mechanisms of the machine, and an accumulator and revolutions counter carriage 51, which is mounted for endwise shifting movement transversely of the body, or frame, portion 50. The carriage 51 has

mounted therein a series of accumulator dials 52 and also a series of revolutions counter dials 54, which are viewable through suitable windows, or apertures, 53 and 55, respectively, provided in the cover 56 of the carriage. The carriage may be shifted by power in either direction across the machine by manipulation of a left shift key 57 or a right shift key 58, both of which are preferably located on the right-hand side of the machine frame 50.

Numerical values may be selected for entry into the accumulator dials 52 of the machine by depression of appropriate numeral keys 60 of a conventional "full" keyboard. The keys are arranged in a plurality of orders, each order containing value keys of from "1" to "9," inclusive. The values so set on the keyboard may be set into the accumulator register dials 52 either additively or subtractively, as by depression of the plus bar 61 or the minus key 62, respectively. Values set into the keyboard may be erased, or cleared, therefrom by depression of another key in the same order, and particularly by depression of the aligned "0" key 59; or by manipulation of the keyboard clear key 63; or, if it is desired that the keyboard be cleared after each cycle of digitation, an add key 64 may be operated forwardly and latched in the operated position, as is well-known. Division operations are initiated by depression of divide key 68 and the extraction of square root is initiated by depression of the square root key 69 aligned with the decimal point of the radicand (as explained in my said joint patent).

The accumulator dials 52 and the revolutions counter dials 54, may be cleared, or reset to "0," by manipulation of the manually operable reset knobs 65 and 66, respectively, these knobs being mounted for lateral sliding movement in the framework of the carriage. Alternatively, either one or both of these accumulator or counter registers may be zeroized by power through the depression of a carriage clear key 67.

The machine with which my invention is preferably associated, is also provided with a multiplying mechanism which comprises the auxiliary ten-key keyboard containing a single value key 70 for each of the values of "0" and "1" to "9," inclusive. The auxiliary, or multiplier, keyboard is placed on the lower left-hand corner of the front of the machine, as shown in FIG. 1, and is operable to insert values into a multiplier mechanism by depression of value keys, digit by digit. The multiplier mechanism set by the depression of the value keys 70 is shifted to the left as values are inserted therein, displaying check dials which show the values so inserted through a window 71 located above the value key 70. The keys 70 preferably are arranged in a square, 3 x 3, with the "0" in front and below the value keys, as shown. Multiplication operation control keys preferably are located adjacent the multiplier keyboard 70 and include: a multiply key 72, which is operable to shift the carriage to the extreme left-hand position shown in FIG. 1, to then zeroize the register dials 52 and the counter dials 54, or either of them, depending upon setting of control mechanisms not here pertinent, and to then multiply the value set in the keys 60 by the values set on the keys 70; an accumulate multiply key 73, which is effective to shift the carriage to the extreme left-hand position shown in this figure and to then initiate a multiplication operation (without clearing the registers), whereby the products of various multiplication operations can be accumulated in the accumulator dials 52; and a negative multiply key 74, which initiates the operation of the machine through the same steps as the accumulate multiply key 73 (i.e., shift the carriage to the extreme left-hand position and then initiate a multiplication operation) with the difference that the value standing in the full keyboard 60 is entered into the accumulator register dials 52 subtractively instead of additively, in order to subtract one product from another. The multiplier mechanism and the controls associated therewith will be more fully described hereafter.

1. Selecting and actuating mechanism

The main operating mechanisms of the machine are supported, for the most part, on or from a frame which comprises a base plate 80 (see FIG. 6) to which is rigidly secured a right side frame 81 (see FIGS. 3 and 4) and a left frame plate 82 (see FIGS. 2 and 6). The right and left side frames are interconnected by means of various crossframe members including crossbars 83, 84 and 85 shown in cross-section in FIG. 2, and the front crossbar 87 shown in FIG. 16.

It was mentioned previously that the value keys 60 of the keyboard are ordinarily arranged, the keys of each order representing the values "1" to "9," inclusive, and a clear, or "0," key 59, as shown. The various keys 60 are arranged for vertical movement in the machine, as by means of key slots 90 (FIG. 2) embracing tie rods 91, and are resiliently biased to a raised position by suitable springs, not identified. There is a latching slide 92 associated with each order of the keyboard keys. These slides are provided with apertures 93 through which the key stems 60 extend. The latching slides 93 are normally urged toward the front of the machine (toward the left in FIG. 2) by means of conventional springs, not shown. Each key stem 60 carries a cam projection 94 and a notch 95 associated with each aperture 93 of the associated latch slide. Whenever a key is depressed, the cam forces the latching slide rearwardly (to the right in this figure), thereby releasing any key in that order which may have been latched in a depressed position. When the key reaches its fully depressed position, the notch 95 registers with the latching slide 92, whereupon the latch slide snaps forwardly from the force of its spring, so that it engages the notch and locks the slide in the depressed position. It can be mentioned here, that if the latching slide is locked against rearward movement, by any suitable means, the keys of that order cannot be depressed.

The values to be entered into the accumulator dials 52 may be determined by means of a plurality of similar selecting mechanisms associated with each order of the value keys 60. In the preferred form of my invention, there is a pair of similar value selecting, or V-notch, bars 96 associated with each order of keyboard keys 60, as shown in FIG. 2. These bars are mounted for end-wise movement by means of a suitable parallel linkage, including links 97, and extend through suitable slots provided therefor in the crossbar 83. Each selecting bar 96 is provided, at its rear end, with a yoke 98 that engages a grooved collar on a ten-tooth selection gear 99, slidable and nonrotatably mounted on a longitudinally extending square shaft 100 journaled in the crossbars 83, 84 and 85. The forward portion of the selection bars are provided with differentially set cam faces 101 which cooperate with pins 102 mounted on the lower end of the key stems, whereby the selection bars 96 are translated, and selection gears 99 are moved along square shaft 100, a differential amount determined by the value key operated. Hence the depression of a value key 60 results in a differential translation of the associated selection bar 96, which, in turn, serves to differentially position the selecting gears 99 axially along the square shaft 100. The lower portion of the V-notch is provided with a socket 103 adapted to receive the pin 102, so that when the related key is locked in its operative position, the selection bar is locked against displacement.

The differential movement of the selecting gears 99 on the square shafts 100 serves to position the gears in the path of a series of stepped teeth provided on an actuating cylinder 105 secured to an actuator shaft 106, all of the actuator shafts being driven in unison by means of miter gearing connecting them with a main drive shaft 107. The shaft 107 is cyclically and unidirectionally operated by means of a clutch-controlled driving means, herein after to be described, so as to provide a single path of

power flow from the electric motor, not shown, to the various power-operated mechanisms of the machine. All of the actuators cycle in unison with rotation of the drive shaft 107, and hence are operative to rotate the selection gears 99 and the square shaft 100 on which the latter are mounted, differential amounts depending upon the differential axial position of the gears on the square shaft 60.

Each of the square shafts 60 is provided on its rear end with a slidably but nonrotatably mounted spool 110, which is formed with an integral plus gear 111 and a minus gear 112. The plus and minus gears are adapted to cooperate with a similar gear 113 mounted on the lower end of each of the accumulator dial shafts 114, the shafts being rotatably journaled in the carriage frame bar 115. When the machine is in its idle, or full-cycle, position, the accumulator gears 113 lie approximately halfway between the add and subtract gears 111 and 112, respectively, so as to permit lateral shifting movement of the carriage without registration of the related gears. In order to enable an amount set up on the keys 60 to be added into the accumulator dials 52, the spools 110 and the integral gears are shifted toward the rear of the machine to cause gear 111 to mesh with gear 113. Conversely, when the amount set in the keyboard is to be subtracted from a value standing in the register, the spools 110 are shifted forwardly so as to cause engagement of the minus gear 112 with the accumulator gear 113. Both shifting movements can be accomplished by means of a flat bar, or gate, 116 (often referred to as a digitation control gate), extending transversely of the machine and lying within the space provided between the add and the subtract gears 111 and 112. The gate 116 is supported at either end by a pair of similar arms 117 which are affixed to a transverse digitation control shaft 118. The shaft may be rocked either clockwise or counter-clockwise by means hereinafter mentioned, so as to cause engagement of the add gear 111 or subtract gear 112 with the accumulator gear 113 and thereby control digitation in the machine.

It will be understood that the machine with which my invention is associated will be provided with a conventional tens-transfer mechanism, so as to effectively transfer a value of "1" to an adjacent higher order, additively or subtractively, every time the dials of a lower order pass through the "9" to "0" position. In the machine preferred for cooperation with my invention, the tens-transfer mechanism will be of the type shown in the afore-mentioned patents, and for other types of calculating machines, the conventional transfer mechanisms of such machines could be used. As such a transfer mechanism has no particular connection with the mechanism of my invention, it will not be described.

2. Revolutions counter

It is conventional to provide a revolutions counter, or a quotient register, in all calculating machines. In the preferred form of my invention, this counter comprises the ordinarily arranged dials 54 which are viewable through the windows 55 in the carriage cover 56. In their preferred form, the dials 54 are mounted upon longitudinally extending shafts 123, which are journaled at their rear ends in the carriage frame bar 115 and at their forward ends in a channel 124 which forms the front part, or rail, of the carriage framework. A counter gear 125 is rigidly secured to each counter shaft 123 and is adapted to be operated by a counter actuator 126 of conventional construction. This mechanism is operable to provide a count of the cyclic operations of the calculating machine, and also for causing a unit to be transferred from a lower order to a higher order each time a wheel 54 passes through the "9" to "0" position. The revolutions counter shown is fully described in the above-mentioned Patent No. 2,229,889 to which reference may

be had for a more complete disclosure of this part of the machine.

3. Motor drive

It is conventional, in machines of the character described, to provide a power-operated driving means for effecting registration in the accumulator of the value set on the amount keys, or, in other words, to drive the drive shaft 107. The drive shaft 107 is operated in a cyclic fashion and, in the preferred machine with which my invention is associated, in a unidirectional manner, by means of a clutch-controlled drive from an electric motor, not shown. As shown in FIG. 3, a motor driven shaft 130, which may be the armature shaft or a stub shaft connected thereto by a suitable flexible coupling, carries a pinion 131 rigidly mounted thereon. The pinion 131 meshes with an idler gear 132, which gear, in turn, meshes with a larger gear 133 rotatably mounted on the transverse drive shaft 107. The gear 133 is provided with a hub on which is formed a driving clutch element, or ratchet, not shown. A driven clutch element 134 is rigidly secured to the drive shaft 107 and carries a spring-urged pawl 135 which is provided with a tooth adapted to engage the teeth of the ratchet for establishing a driving connection between the gear 133 and the driven disk 134 and its shaft 107. The pawl 135 is normally spring-urged into drive engaging relationship with the ratchet, but is restrained in the open, or disengaged, position by means of a clutch control lever, or dog, 136 pivotally mounted on the right side frame 81 by some suitable means, such as stud 137. It is conventional in machines of the character described, to provide the clutch control lever 136 with a roller 138 which seats in a depression formed on the periphery of the driven disk 134, in the full-cycle position thereof, and in all other positions of the disk 134 maintains the control lever 136 in its disengaged (i.e. clutch engaging) position. It is obvious, therefore, that one or more cycles of the drive shaft 107 can be determined by proper operation of the clutch control lever 136.

It is preferred that the electric circuit for the driving motor be established simultaneously with the movement of the clutch control dog 136 (in a counter-clockwise direction, as viewed in FIG. 3), so the clutch is engaged and the motor started at the same time. For this purpose the upper end of the clutch control lever 136 is connected to the rear end of a link 140 by any suitable means, such as a long stud 141. The forward end of the link 140 is pivotally supported on a lever 142, as by means of stud, or pin, 143. The lever 142 is pivotally mounted on the frame plate 81 by any suitable means, such as stud, or screw, 144. The lower end of the lever 142 carries a long pin, or stud, 145 which extends through a suitable aperture in the frame plate 81, and, on its inside end, supports the front end of a long switch link 146. It will be obvious that the switch control link 146 is translated forwardly in the machine (to close the motor switch, not shown) simultaneously with the rocking of the clutch control dog 136 to its clutch-engaging position. It will also be obvious, as seen in FIG. 3, that the lever 142 is rocked, and hence the clutch dog 136 and the switch link 146 are moved to their operative positions, by the rocking of the lever 374 (clockwise in this figure), as will hereinafter be described under the heading of "Multiplier Mechanism." It will be observed, likewise, that the roller 138, in maintaining the clutch control lever 136 in its clutch-engaging position throughout the machine cycle, will also serve to maintain the switch control link 146 in its operative position, so that the motor circuit can be interrupted only in the full-cycle position of the parts.

4. Carriage shift mechanism

Calculating machines of the character described conventionally are provided with means for shifting the carriage 51 selectively, in either direction, through one or more ordinal spaces. In the preferred form of machine,

the shifting means is operated from the an actuator shaft 106 under the control of the manually depressible shift keys 57 and 58, and certain automatic means, one example of which will be described in connection with the multiplier mechanism. The shift keys, and the mechanism controlled by them, are fully shown and described in U.S. Patent No. 2,380,642 issued to Carl M. Friden et al., on July 31, 1945, as modified by the shift clutches shown in the patent to Matthew, No. 2,679,916 issued June 1, 1954. The manually controlled shifting mechanism is not only conventional, but has no particular connection with the mechanism of my invention. It suffices to mention that the left shift key 57 causes a rearward translation of left shift rod 160 (FIG. 4) and depression of the right shift key 58 causes rearward translation of the right shift rod 161. The push rods 160 and 161 are normally maintained in their forward, or inactive, positions shown in FIG. 4, by suitable compression springs 162, while the rear ends of the rods carry clutch control arms 163. A pusher link, or shift interponent, 158 engages the forward end of left shift rod 160, and, when operated, pushes the rod 160 rearwardly. Similarly, a pusher link, or shift interponent, 159 engages the forward end of the right shift rod 161, and can be operated to push the rod 161 rearwardly. The respective clutch control arms 163 cooperate with the driving clutch member 164 and 165, respectively, located on the rear ends of the second and first actuator shafts 106, these shafts being extended to the rear of the machine for this purpose. Cooperating with the driving elements 164 and 165 are the driven elements, or clutch disks, 166 and 167, respectively. These disks are affixed to sleeves 168 and 169, respectively, which are rotatably mounted at the rear of the machine. Sleeve 168 carries a pinion 170 which meshes with a gear 171, as shown in FIGS. 4 and 5. The idler 171 meshes with a gear 172 rigidly mounted on the rotatable sleeve 173. The right-hand drive sleeve 169 is provided with a pinion 174 which meshes with a wide idler, or pinion, 175 which, in turn, meshes with the large idler 171. Thus, when push rod 160 is moved toward the rear of the machine, thereby causing the left shift clutch element 164 to engage the driven disk 166, the gear 172 and sleeve 173 are rotated in one direction, while the rearward translation of push rod 161 and the consequent enablement of the clutch 165, 167 causes rotation of the gear 172 and sleeve 173 in the opposite direction. The sleeve 173, as shown in FIG. 4, carries a drive disk 176 which is provided with four equidistantly spaced pins 177 adapted to engage in the notches 178 in the shift rack 179 mounted on the rear of the carriage frame bar 115. Thus the operation of the push rod 160 is effective to shift the carriage to the left while the operation of the shift rod 161 is effective to cause a shift of the carriage toward the right. Preferably the gear trains are so designed that each revolution of the actuator shafts 106 will cause a 90° rotation of the drive plate 176, whereby the carriage will be shifted in each machine cycle through a distance equal to the spacing between the notches 178 (which is equal to the distance between the numeral wheel shafts 100). In other words, the carriage will be shifted one ordinal space in either direction, on each cycle of operation of the power shaft 107, as determined by the operation of the push rods 160 or 161.

It is customary, in machines of the character described, to provide some means for disabling the control of the shift rods 160 and 161 whenever the carriage reaches either of its extreme end positions. It is conventional in the machine shown to achieve this purpose by providing means for lifting the shift interponents 158 and 159, respectively, out of engagement with their respective shift clutch control rods 160 and 161 when the carriage reaches its extreme left-hand or extreme right-hand position. It can be mentioned that the mechanism of my invention will be operative, upon depression of a control key, to first shift the carriage to the extreme left-hand position

(and, on some operations, to clear the accumulator register while in this position), and then to initiate the multiplication operation. For this reason I will describe the mechanism which will disable the carriage shifting means when the carriage reaches its extreme left-hand position, but will omit a description of the automatic means which is operative to terminate a shift in the other direction at the extreme right-hand position. The mechanism for this purpose is shown particularly in FIGS. 4 and 5.

10 The terminal notch 178 on the right end of the shift rack 179 (at the left side of FIG. 5, as the true right-hand direction is indicated by the arrow R) is formed, in part, by an override pawl 190 pivoted on the rack 179, as by stud 191. The pawl is resiliently biased into shift position by a suitable spring 189, in which position its nose 192 forms a part of the end notch 178. The lower edge of the pawl 190 is provided with an arcuate cam shoulder 193 adapted to be engaged by a rotating pin 177 when the drive plate 176 attempts to move the carriage to the left beyond the extreme terminal position, thereby rocking the override pawl on its pivot (counterclockwise in FIG. 5). The outer, or right-hand, end of the pawl 190 is formed as a nose 194 which, in that position of the carriage, overlies an ear 195 of the upright portion 196 of a long L-shaped lever 197 pivoted near the center of the machine, as by screw 198. The upright portion 196 is held from rearward displacement, or bending, by means of a flatheaded screw 199 which extends through a slot 200 in the upright portion. The right end of lever 197 overlies the horizontal arm of a bellcrank 201, which is pivotally mounted on the digitation control shaft 118. The forward vertical arm of the bellcrank 201 is pivotally connected to a forwardly extending link 202 (FIGS. 4 and 5). The forward end of this link is pivotally connected to an upstanding arm 203 of a transverse bail 204. The bail 204 is pivotally mounted on a transverse shaft 205, and carries a curved arm 206 which curves around the shaft 205 and extends rearwardly under the left shift control pusher arm 158. The rocking of the override pawl 190, by means of the linkage shown and described, translates the link 202 forwardly, rocking the bail 204 (counterclockwise when viewed from the right side of the machine), thereby causing the arm 206 to lift the left shift control link 158 from engagement with the push rod 160, and thus disabling the left shift clutch. It can be noted at this point that the bail 204 is formed as shown in FIG. 4, and is provided with a leftwardly extending arm 207 which underlies an interponent arm 390 of a left shift control mechanism operated by the multiplying mechanism, to be described hereafter. The extension 207 also underlies a pusher link, or control arm, 239 which controls operation of the clutch that drives the power-operated clearing mechanism, likewise disabling that mechanism when the bail is rocked. Thus the rocking of the bail 204 lifts both interponents 158 and 390 to disable all controls of the left shift clutch, and also disables the register clearing mechanism.

5. Register clearing mechanism

60 It is also conventional in machines of the class described to provide means for clearing the accumulator register dials and the counter dials to "0." The conventional mechanism, for the machine with which my invention is preferably associated, comprises a pair of clearing racks 220 (see FIG. 2) for the accumulator dials 52. These racks are slidably mounted in the carriage frame bar 115 and cooperate with a mutilated clearing gear 221 mounted on each of the dial shafts 114. Movement of the clearing racks 220, lengthwise of the carriage frame bar 115, causes them to engage any of the mutilated gears 221 displaced from a "0" position and to rotate the dial shaft and dial to the "0" position, as fully explained in the patent to Friden No. 2,229,889. These clearing racks can be operated manually by means of knob 65 shown in FIG. 1. Similarly the counter register dials 54 can be

returned to a cleared, or "0," position by means of the counter clear racks 222 which cooperate with mutilated clearing gears 223, one of which is mounted on each of shafts 123. The counter clearing racks 222 can be operated manually by means of the knob 66 shown in FIG. 1. Either or both registers can also be cleared by a power operation which is initiated by the depression of the carriage clear key 67, or automatically in certain programmed operations, by means of the operation of a power-operated clear slide 224 (shown in FIGS. 1 and 5). This clearing slide is enabled to reciprocate the clearing knobs 65 and 66 by means of interponents 228 and 229 (FIG. 1) which are rigidly secured to the knobs 65 and 66, respectively. These interponents are adapted to engage pins 230 and 231, respectively, mounted on the slide 224 and can be rocked away from engaging position by rotation of the knobs 65 or 66. Thus either one or both of the registers can be cleared from operation of the power slide 224, the operation of which will now be described.

The power-operated clear slide 224 is mounted for lengthwise movement on the frame bar 115 of the carriage frame, as shown in FIG. 5, by any suitable means, such as slots 225 in the power bar engaging pins 226 carried by the frame member 115. The power slide is normally biased to the left (to the right in FIG. 5) by means of a strong spring 227 tensioned between a pin 226 and a stud 232 on the power bar 224.

The mechanism for operating the power bar 224 is shown particularly in FIGS. 4 and 5. A push rod 240, shown at the left of FIG. 4, controls the operation of the clearing mechanism. This rod is normally biased to its forward, or inoperative, position by means of a compression spring 241 compressed between the cross-member 83 of the machine and a collar on the push rod, as shown. The clutch control rod 240 can be shifted rearwardly by suitable means, such as pusher link, or interponent, 239. This link 239 is pivotally mounted on an arm 238 rigidly secured to the cross-shaft 205, the operation of which is controlled by various means, some of which will be hereafter mentioned. The push rod 240, at its rear end, carries a yoke 242 which embraces an annular slot formed in a clutch collar 243 longitudinally shiftable but nonrotatably mounted on the highest order actuator shaft 106. The collar 243 forms the driving portion of a conventional jaw clutch, the driven portion comprising a sleeve 244 rotatably mounted on the rear cross plate 85 and a bracket 245 mounted on plate 85. The sleeve 244 carries a cam 246 rigidly mounted thereon, the profile of the cam being shown in FIG. 5. Associated with the cam 246 is a follower arm 247 and a roller 248, which engages the periphery of the cam, the arm being pivotally mounted on the back of the machine, as by pin 249, and being biased into engagement with the cam 246 by a suitable spring 250. The upper end of the arm 247 is slotted, as at 251, the slot embracing a pin 255 mounted on a slide 256 which is slidably mounted on the rear cross plate 85 by any suitable means, such as brackets 257. The slide 256 carries a forwardly projecting ear 258 which is adapted to engage the free end of an interponent 259 pivotally mounted on bracket 261 attached to the power slide, 224. The interponent 259 is normally lifted above the plane of the ear 258 by means of a conventional live pawl 262 engaging a bracket 263 mounted on cross-member 85, when the carriage is in the ordinal position adjacent the extreme left-hand position. The construction is such that as the live pawl moves off of the bracket 263, the interponent 259 drops into a position in which it will be engaged by the ear 258 simultaneously with the carriage moving into the extreme left-hand position.

The rocking of the bail 204, from the operation of the override pawl 190 as previously described, is also operative to disable the clutch 243, 244 of the register clearing mechanism. It was previously mentioned that the bail 204 is formed as shown in FIG. 4, the left-hand portion 207 thereof underlying the interponent 239 which

moves the push rod 240 to its clutch-engaging position. Thus the rocking of the bail 204 lifts the interponent 239 from its engagement with the forward end of the rod 240, the interponent being biased downwardly into engagement with the rod by means of a suitable spring, not shown. By means hereinafter mentioned, the clear clutch can be set in its operative condition simultaneously with the initiation of a left shift operation, both the left shift and the clear clutch being held in the operative condition throughout the shifting operation. When the carriage reaches the extreme left-hand position, the clearing mechanism is operated simultaneously with the rocking of the override pawl 190, whereupon the bail 204 is operated to disengage both of said clutches.

6. Multiplier selection mechanism

It has been mentioned that, in the machine with which my invention is preferably associated, the multiplier mechanism includes an auxiliary keyboard comprising the keys 70, located in the lower left-hand corner of the machine. It is conventional, in the machine of this make, to arrange the multiplier keys in a small 3 x 3 square for the value keys "1" to "9," inclusive, with a large "0" key in front of the grouping. The mechanism controlled by these keys is shown particularly in FIG. 6. These keys are mounted in a multiplier, or auxiliary, keyboard frame 270 and are biased to their raised position by springs, not shown. Each of the value keys is provided with a formed arm 271, each so formed as to overlie an escapement bar 272. Each of the formed arms 271 is provided with a downwardly projecting nose 273, which noses are arranged in a staggered relationship projecting through the lower plate of the keyboard frame 270. The downwardly projecting noses 273 on the value keys "1" to "8" register with an upwardly projecting nose 274 on a value selection lever, or bellcrank, 275. The selection levers 275 are arranged in a compact lateral position, and each is pivoted upon a common shaft 276. The bellcranks 275 are provided with a lower projecting nose 277, these noses being differentially spaced, in an inverse relationship, from the pivot shaft 276 according to the value of the respective key. All of the noses project through a common aligning slot, not shown, formed in a guide plate 278, and are normally biased to their inoperative position shown by springs 280 which cause them to rest upon a bracket member 279.

The operation of the various noses 277 of the selection bellcranks 275 are operative to set selection, or control, segments mounted in a shiftable multiplier carriage 290. The carriage comprises a pair of base plates 291 and a pair of end plates 292, the whole unit tied together by suitable tie rods 293. The carriage is mounted for transverse movement in the machine, as upon shaft 294 and a carriage rail, not shown. The multiplier carriage 290 is normally biased toward the left of the machine by a lever 295 pivoted to the base plate 80, as at 298 (see FIG. 9), and strongly biased by a heavy spring 297. The carriage, in its inoperative position, is to the right of the window 71 in FIG. 1, and is normally held in that position by an escapement mechanism, not shown, but which is operated by the escapement bar 272.

The lower plates 291 of the multiplier carriage support a plurality of orders of pins 300, corresponding to the values "1" to "8" in each order. The pins, in their retracted, or inoperative, position, lie slightly above the noses of the inoperative bellcranks 275. Thus, when a bellcrank 275 is rocked, projecting the nose 277 upwardly, the corresponding pin 300 is shifted from the position shown in FIG. 6, upwardly to a second adjusted position. Associated with each order of pins 300 is a differentially settable segment 301 pivotally mounted on a shaft 302. Each of these segments carries a dial section 303 which is viewable through the window 71, as the carriage 290 is shifted, order-by-order, toward the left with the insertion of multiplier values into the machine.

The segments 301 are biased to a fully operative position (clockwise from the position shown in FIG. 6) by a suitable spring 304, and are latched in their inoperative, or "0" value, positions shown by a latch member 305. Immediately after one of the value pins 300 is set to its operative, or raised, position, the latch 305 of that order is released by means of a latch releasing lever 306. The lever 306 is operated by means of a link 307 which is pivotally connected to the lever and to a bellcrank 308 pivotally mounted adjacent the lower plate of the keyboard frame 270 by any suitable means, such as stud 309 on a formed portion of bracket 279. This bellcrank 308 has a nose 310 projecting through the lower plate of the keyboard frame 270, where it underlies the escapement bar 272. Thus the depression of any of the value keys "1" to "9," inclusive, not only operates the escapement mechanism, not shown, but also rocks the bellcrank 308 to release the latch 305. Upon release of the latch 305, the associated segment 301 moves to an adjusted position under the force of spring 304, the rotation of the segment being blocked by a projected pin for the values "1" to "8" and by a suitable stop, not shown, for the value "9." Thus the depression of any of the value keys "1" to "9" is operative to set a multiplier segment 301 to a differentially adjusted position corresponding to the value key depressed. It can be noted at this point that the depression of the "0" key is effective to cause operation of the escapement mechanism, not shown, by a secondary means, not illustrated, whereby the latch 305 is not released and the related segment 301 remains in the position shown, although the multiplier carriage 290 is shifted one space to the left.

7. Multiplication mechanism

The initiation of a multiplying operation is governed by the depression of one of the multiplier control keys 72, 73 or 74. The multiplier key 72 initiates a program of operation which includes shifting of the carriage to the extreme left-hand position shown in FIG. 1, then clearing the registers, and finally initiating a multiplying operation in a positive direction. The depression of the accumulate control key 73 programs the operation of first shifting the carriage to the extreme left-hand position shown and then initiating a multiplying operation in a positive direction, without clearing the registers, so that the product is added to whatever value stands in the register. The negative multiply key 74 operates similarly to the accumulate multiply key 73, except that it initiates a multiplication operation in a subtractive direction, whereby one product can be subtracted from another previously in the accumulator dials. The principle of multiplication involved comprises cycling the machine a number of times determined by the differential position of the various segments 301, with the digitation control gate 116 operative to either add or subtract the value standing in the main keyboard, coupled with shifting both the multiplier carriage 290 and the accumulator carriage 51 between each ordinal operation. The method of controlling the ordinal operation will first be described, having reference to the mechanism shown particularly in FIG. 6.

It will be recalled that the segments 301 were differentially positioned from the depression of the multiplier value keys 70. The respective segments 301 are provided with rack teeth 311 on their rearward portion. The machine is provided with a single feed pawl 320 adapted to register with the rack 311 lying in the position first removed from the home, or inoperative, position of the multiplier carriage 290. The pawl 320 is pivotally mounted on an arm 321, as by stud 319, and is biased toward engagement with the rack by a suitable spring 322. In normal conditions, when the multiplying mechanism is not operative, the feed pawl 320 is blocked from engagement with the associated rack 311 by means of a restraining arm 323 rigidly secured to a stub shaft 324, the

operation of which will hereinafter be mentioned. The feed arm 321 is reciprocated with each cycle of machine operation by means of an eccentric follower 325 mounted on an eccentric, not shown, on the power shaft 107. The restraining arm 323, when rocked (counter-clockwise) from the restraining position shown, also operates as a check pawl, so that as the rack 311 is fed, tooth-by-tooth, by the operation of the feed pawl 320, the arm 323 latches the rack in its adjusted position.

10 The operation in each order continues until the segment 301 has been fed to its original, or "0," position, whereupon the upper end of the rack engages a shoulder 326 mounted on the forward end of a multiplier shift control lever 327, rocking the shoulder 326 and lever 327 to the position shown in FIG. 6. Such rocking of the lever 327 initiates a programmed operation which includes rocking the shaft 324 (clockwise to the position shown in FIG. 6) to disable the feed pawl 320, and the enabling of the shifting mechanism to effect a single step shifting of the accumulator carriage 51 and the multiplier carriage 290. The means for programming these operations will be described shortly but for the moment it should be noted that the shifting of the multiplier carriage 290 is caused by the operation of a shift pawl 335 engaging a rack 296 mounted on the rear side of the multiplier carriage 290.

20 The shift pawl 335 is operated by an eccentric (not shown) mounted on a hub, or collar, 336. The hub 336 is slidably but nonrotatably mounted on a shaft 337 which is driven from the drive shaft 107 through suitable miter gears 342, as shown. Normally the hub and eccentric, and consequently the shift pawl 335, lie below the plane of rack 296, as shown, being biased to their lower positions by a light compression spring 338 which encompasses 25 shaft 337 and bears against a collar 341 on the shaft. However, the assembly of the hub, eccentric and pawl are lifted to a position in which the shift pawl 335 lies in the plane of the rack 296 by rocking of a shaft 518, the operation of which is controlled by the rocking of the multiplier shift control lever 327 previously mentioned. An arm 339 is rigidly mounted on the shaft 518, and is provided with a pin 340 which is adapted to engage the underside of the annular collar 341 on the hub 336, so that 30 rocking of the shaft (clockwise in FIG. 6) will lift hub 336 and pawl 335 to operative position. When the pawl 335 is in its operative position, it is effective to shift the multiplier carriage 290 a single order to the right with each cycle of operation. This shifting operation can continue until the multiplier carriage 290 is returned to its inoperative, or home, position to the right of window 71 shown in FIG. 1. The rocking of the shaft 518 is also effective to initiate a single shift of the register carriage 51 a single step to the right, as will be explained hereafter.

35 The multiplier selection means herein briefly described, the multiplier carriage, and the multiplier mechanism comprising the feed pawl 320 and the carriage shift pawl 335 are conventional, and are not utilized in the operation of the multiplying mechanism of my present invention. However, they have been described as I prefer to use the conventional multiplier control keys 72, 73 and 40 74 to control the multiplying or squaring operations of the present invention, so as to provide for automatic clearing of the accumulator register dials 52 as a preliminary to the multiplying operation, or not, as desired by the operator, or to perform the operation additively or subtractively as required. It is therefore necessary, in my mechanism, to provide a conditioning means which is effective, among other things, to disable the operation of the feed pawl 320 and the shift pawl 335 so as to permit control by my new mechanism. This is secured by blocking rotation of the shaft 324, thereby holding the feed pawl 320 disabled throughout the present multiplication operation, and by lifting the shift pawl 335 higher than normally so as to prevent its en-

gagement with the rack 296, although the eccentric mechanisms associated therewith will be operated idly in all operations. As indicated, I prefer to use the conventional multiplier control keys 72, 73 and 74 to initiate the present multiplying operation, and it is therefore necessary to understand the operation of these keys, and the mechanisms which they control, and these will now be described, referring first to the mechanisms controlled by the multiply key 72.

It was indicated above that the depression of the multiply key 72 is operative: (a) to initiate a cyclic shifting of the carriage to the left until the carriage reaches its extreme left-hand position; (b) to condition the power clearing mechanism for operation when the carriage reaches the extreme left-hand position; and (c) to initiate a multiplication operation with the carriage in the extreme left-hand position (the carriage 51 shifting to the right, order-by-order, in synchronism with the shifting of the multiplier carriage 290).

The key 72 (FIG. 7) is mounted for vertical movement in the machine, and is biased to a raised position by spring 350. The multiply key 72 is latched in the depressed position by means of a suitable latch arm 360, the ear 361 of which engages over a shoulder 362 on the key stem, when the key is depressed. The latch arm 360 is rigidly mounted on a short transverse shaft 363, which also carries the latching arms for the keys 73 and 74, as will be mentioned hereafter. A roller 351, on the lower end of the key stem, is embraced within a slot 352 in the forward end of a formed lever 353. The lever 353 is pivotally mounted on the intermediate frame plate 88 by any suitable means, such as stud 354. It will be obvious that the lever 353 is rocked (counterclockwise in FIG. 7) by the depression of the multiply key 72, and is held in the rocked, or depressed, position by the latching of key 72 by latch 360.

The lever 353 carries a roller 355 that engages the forward edge of an arm 370 which is rigidly mounted on a transverse shaft 371. The shaft 371 extends across the machine and is journaled in the right-hand frame plate 81 (see FIG. 3). Adjacent the right-hand frame plate, the shaft 371 carries an arm 372 rigidly secured thereto. A stud 373, carried by the arm 372, engages the forward end of a lever 374 pivotally mounted on a transverse shaft 205. The rear arm of the lever 374 extends rearwardly and upwardly, and terminates in a hook formation 376 which engages the long stud 145 connecting the clutch control lever 142 and the switch control link 146. Thus the depression of the multiplier key 72 is effective to rock the shaft 371 (clockwise in FIG. 7 and counter-clockwise in FIG. 3), and to hold it in the rocked position. The lever 372, mounted on shaft 371, rocks the lever member 374 (clockwise in FIG. 3), thereby pulling the switch link 146 forwardly to close the motor switch and to rock the clutch control levers 142 and 136 (counterclockwise in FIG. 3) to cause engagement of the clutch. By this means the depression of the key 72 is effective to initiate machine operation, and as the key is latched in its depressed position, the machine runs until the latch 360 is released at the end of the multiplying operation, automatically, as will now be described.

The short shaft 363, on which the latch is located, extends from the intermediate frame plate 88 to the left-hand auxiliary, or control, plate 86 (FIG. 10). Adjacent its left end it carries a latch arm 364 (FIG. 9) fixed thereto, the upper end of which is provided with a latching ear 365. The lower end, or tail, 366 of the latch lever 364 terminates adjacent the base plate 80 and is associated with a lever member 367. The lever 367 is riveted to, and therefore rocks with, lever 295, so its angular position corresponds to the ordinal position of the multiplier carriage 290. When the carriage is returned to its home position, the lever 367 barely engages the lower end 366 of the latch arm 364. Then, when the multiply carriage

is shifted to the extreme right during the overshift cycle following the last ordinal multiplication operation, the lever 367 is rocked rearwardly, thereby rocking the latch lever 364 (clockwise in FIG. 9) to release both latches 364 and 360 and thus terminate the multiplication operation.

The rocking of the shaft 371 from depression of the multiply key 72 is also utilized to control the operation of the left shift clutch and the clearing clutch, in order to first shift the carriage to the extreme left-hand position and to then clear the register. The mechanism for this purpose, which is similar to that shown and described in the patent to Machado No. 2,650,761 issued September 1, 1953, is shown particularly in FIGS. 4 and 8. The shaft 371 carries an arm 380 located approximately midway between frame plate 81 and intermediate plate 88. The upper end of the arm 380 carries a link 381, the rearward end of which is pivotally connected to reciprocating hook member 382. The hook member 382 is mounted on an eccentric carried by a power-operated shaft 383 which is geared to drive shaft 107, whereby the hook member is reciprocated in each cycle of machine operation. In the arrangement of the parts shown in FIG. 8, the reciprocation of the hook 382 is an idle operation. However, when the shaft 371 is rocked (clockwise in FIG. 8) and the hook member 382 is rocked to the right from the position shown, then the hook 384 on the outer end thereof engages a pin 385 of bellcrank 386. In that situation, the hook 384 rocks the lever 386 (clockwise in this figure) and the shaft 205 to which it is rigidly secured. The lower end of the bellcrank 386 carries a pin 387 which engages the latch shoulders of a latch member 388, thus holding the shaft 205 in the rocked position. The shaft 205 also carries an arm 389, the upper end of which pivotally supports a pusher link 390. A shoulder formed on the rear end of link 390 engages a pin 391 on an arm 392 formed on a sleeve 393. The sleeve 393 is rotatably mounted on a shaft 394 and carries a second arm 395 (see FIG. 4), on the outer end of which is a long pin 396 that engages the left shift clutch push rod 160. Thus the rocking of shaft 205, by means of the pusher link 390 and sleeve 393, moves the push rod 160 rearwardly to its clutch-engaging position. It will be recalled that the shaft 205 is latched in its adjusted position, so that the mechanism just described is held in its operating position to cause a continued cycling of the left shift clutch.

The shaft 205, which is thus rocked from the depression of the multiplier key 72, and held in the rocked position, is also operative to cause the engagement of the clear clutch and thereby operate the clearing mechanism as soon as the carriage reaches the extreme left-hand position. This can be accomplished by means of the arm 238 (FIGS. 4 and 7), which is also rigidly mounted on shaft 205. This arm carries the clear clutch pusher link 239 that engages the push rod 240, as previously described. Thus the rocking of the shaft 205 causes the rearward translation of the clear clutch control rod 240, and thereby causes engagement of the clear clutch and operation of the clear clutch mechanism, as previously explained.

It was mentioned that the latch 388 holds the bellcrank 386 and shaft 205 in the rocked position. The latch is released by means of a pin 397 mounted on the bellcrank 386, which is effective to lift the latch to disengaging position when the shaft 371 is returned to its normal position by the release of the multiply key 72.

The shifting mechanism just mentioned, however, is disabled after the carriage has reached the extreme left-hand position by the mechanism previously described, including the link 202 and bail 204. The bail 204 is formed, as shown in FIG. 4, so as to underlie the link 390, whereby rocking of the bail lifts the link 390 away from the pin 391. Thereupon the spring 162 of the

clutch push rod 160 will return the parts to their normal position, and thereafter the lower edge of the link 390 will ride upon the pin 391 until the parts are returned to their normal condition at the end of the multiplication operation. The clearing clutch is disabled in a similar manner by the rocking of the bail 204. It will be seen in FIGS. 4 and 7, that the formed end 207 of bail 204 underlies a bellcrank 401, which, in turn, has an ear 402 underlying the pusher link 239. By this means, the rocking of the bail lifts the rear end of crank 401 (rocks it counter-clockwise in FIG. 7), which lifts the pusher link away from push rod 240 and spring 241 thereupon disables the clear clutch. When the bail returns to its normal position, the clutch control rod 240 will be in its normal (forward) position, so thereafter the interponent 239 will ride upon the rod but will be ineffective to operate it. Thus, although shaft 205 is latched in its rocked position, and consequently the pusher links 239 and 390 are held in their rearward positions, they are ineffective to position clutch control rod 240 or 160 in the succeeding revolutions of the machine.

The rocking of the arm 401, caused by the operation of the override pawl, previously mentioned, is also effective to initiate a multiplication operation. As shown in FIG. 7, the lever 401 is formed as a bellcrank, the lower arm of which carries a pin 410. The pin 410 normally registers with, and is embraced by, a notch 411 in a longitudinally extending link 412. The link 412 is pivotally mounted on a pin 413, and biased in a downward direction (clockwise in FIG. 7) by means of a spring 414 tensioned between a seat on the bellcrank 401 and an aperture in a projection on the link, as shown. The pin 413, which forms the pivot for the link 412, is mounted on the upper end of an arm 415 which is pinned on, or otherwise rigidly secured to, a short transverse shaft 416. Thus, the rocking of the bellcrank 401 (counter-clockwise in FIG. 7) from the operation of the bail 204, 207, pulls the link 412 rearwardly to rock the shaft 416 (clockwise in FIG. 7, and counter-clockwise in FIG. 10). The shaft 416 extends from the intermediate frame plate 88 leftward to the auxiliary frame plate 86, as shown in FIG. 10. At its left end, to the left of the auxiliary frame plate 86, it carries a latch arm 417 provided with a shoulder 418 that registers with a pin 419 on the forward end of a two-armed lever 420. The latch 417 and shaft 416 are biased to the latching position shown in FIGS. 7 and 10 by means of a spring 421 tensioned between the latch arm 417 and a stud on the auxiliary frame plate 86, previously mentioned, thereby biasing the parts to the position shown.

The lever 420 (FIG. 10) controls the operation of the multiplier mechanism, i.e., the mechanism which controls the feeding of the segments 301 to their "0" position, and the shifting of the multiplier carriage ordinarily from left to right. Normally the lever 420 is latched in its inoperative position shown by means of two latches: the latch 417 just mentioned, and a second latch arm 430, pivotally mounted on the auxiliary frame plate 86 by any suitable means, such as screw 431. The latch member 430 has an upwardly extending nose 432 which normally underlies an ear 433 formed on the forward end of lever 420. The latch member 430 is normally biased into latching engagement with lever 420 (counter-clockwise in FIG. 10) by any suitable spring, such as 434 tensioned between the latch member and a suitable shaft 441. The latch member 430 is moved to releasing position by means of a U-shaped lever 440 which is pinned, or otherwise rigidly secured, to a transverse shaft 441. The lever 440 is provided with a pin 442 which overlies the forward arm of the latch arm 430, whereby the counter-clockwise rocking of shaft 441 and lever 440 rocks the latch member 430 clockwise to release the forward end of lever 420. It can be mentioned that the shaft 441 is rocked in the first cycle of a multi-

lication operation, thereby releasing the lever 420 to the sole control of latch member 417, which, as previously mentioned, is operated by the override pawl when the carriage reaches the extreme left-hand position.

5 The means for rocking shaft 441, in order to disable latch 430, will now be described, the mechanism therefor being shown primarily in FIG. 3. It will be recalled that the depression of the multiplier key is effective to operate the mechanism shown in FIG. 8, particularly 10 the reciprocating hook member 382 which engages and rocks the bellcrank 386 rigidly mounted on the shaft 205 (clockwise in FIG. 8, counter-clockwise in FIG. 3). The shaft 205 extends to the right, as shown in FIG. 3, and adjacent the frame plate 81 carries a rigidly mounted 15 arm 445. This arm is connected, by means of link 446, to a rocking arm 447 mounted on the frame plate 81. A link 448 is pivotally mounted on the upper end of the arm 447, the forward end being supported by an arm 449 rigidly mounted on the right end of the shaft 441. 20 Thus, in the first cycle of machine operation, when the mechanism previously described operates the hook 384 to power-set the left shift and clearing mechanism, the shaft 441 is rocked (counter-clockwise in FIGS. 3 and 10) by the same power-operated mechanism to rock 25 U-lever 440 (FIG. 10) and thereby release the latch member 430.

The control lever 420 (as shown in FIG. 10) is pivotally mounted on the left side control, or auxiliary, plate 86 by any suitable means, such as screw 455. The rearward end of the lever 420 is provided with a pin 456 which is embraced within a slot 457 formed on the forward end of a bellcrank 458. This bellcrank is pivotally mounted on the auxiliary frame plate by any suitable means, such as large-headed screw 459, and is biased 35 to an operative, or counter-clockwise, position, by means of a strong spring 460 tensioned between the rear end of the bellcrank 458 and a suitable seat on the frame plate. The force of spring 460 is sufficient to rock the bellcrank 458 (counter-clockwise in FIG. 10), and thus 40 rock the control lever 420 (clockwise in this figure) when the two latches are released.

The rear end of the lever 420 is formed as an ear 464, upon which is mounted a roller 465. The rocking of the control lever 420 causes the roller 465 to engage the 45 lower cam end of a lever 466, thereby rocking the lever (clockwise when viewed from the front of the machine) about its pivot 467. The upper end of the lever 466 lies against the left face of a gate-setting cam 468 (see FIG. 9) slidably but nonrotatably mounted on the power shaft 50 107. The cam 468 is normally biased to the left to an inoperative position by means of a spring, not shown, and is pushed into an operating position by the rocking of lever 466, as the result of the rocking of the control lever 420. When the gate-setting cam 468 is shifted as 55 described, its periphery is moved into the plane of a roller 475 mounted on the upper end of a follower member 476, whereby the high point of the cam 468 will rock the follower 476 (counter-clockwise in FIG. 9) immediately after the start of the next cycle of machine 60 operation (the release of initiating arm 420 taking place about halfway through the clearing and override cycle, after the clearing operation is completed). The follower arm 476 is pivotally mounted on the control plate 82 by any suitable means, such as upon a transverse shaft 65 487. When rocked to the operative, counter-clockwise, position by the cam 468, the follower arm 476 is latched in the operative position by means of a latch arm 477 engaging a stud 478 on the follower arm.

The upper end of the follower member 476 is provided 70 with a stud 479 which pivotally supports an additive setting arm 480 and a subtractive setting arm 481. The rearward end of these additive and subtractive setting arms, or links, 480 and 481 is provided with shoulders 482 and 483, respectively. It can be mentioned that these 75 links normally lie in the inoperative position shown, but

that the former is resiliently lifted upon depression of the multiply key 72 or the accumulate multiply key 73 and that the link 481 is lifted upon depression of the negative multiply key 74. The shoulders 482 or 483, respectively, are adapted, when their respective links are lifted, to engage pins 484 and 485, respectively, which are mounted on the upper and lower ends, respectively, of a two-armed lever 486 rigidly mounted on the gate-setting shaft 118. Links 480 and 481 are lifted, as mentioned, by depression of their respective operating keys so that their respective shoulders will engage the associated pin, and then, when the follower arm 476 is rocked, rock the lever 486 and shaft 118 to the proper operative position. Normally, however, the follower arm 476 is disabled as the cam 468 lies to the left of the roller 475. The cam, of course, rotates constantly with the rotation of the drive shaft 107, and thus is rotating while the carriage is being shifted to the right. The operation of the override pawl, in operating latch 417 to release control lever 420, is effective, among other things, to shift the cam 468 to the right, whereupon the rotation of the cam, shortly after the start of the next cycle of machine operation, rocks the follower 476 (counter-clockwise in FIG. 9) to cause either link 480 or 481 to rock the lever 486 and shaft 118. Upon depression of the multiplier key 72, the additive link 480 is lifted to engaging position, whereby rocking of bellcrank 476, when the override pawl is operated, will rock the upper end of the lever 486 rearwardly (counter-clockwise in FIG. 9), to cause the add gears 111 of the digitation control spool 110 to engage the accumulator gears 113. The follower member 476 is latched in its operative position by means of the latch member 477, thereby holding the digitation control shaft 118 in the adjusted position and thus causing additive operation of the accumulator dials. On the other hand, depression of the negative multiply key 74 lifts the link 481 so that operation of bellcrank 476 will rock lever 486 in the opposite direction to initiate repeated cycles of subtractive operation.

The rocking of the control lever 420 is also effective to enable the operation of the multiplier segment feed pawl 329, shown in FIG. 6. It is seen in FIG. 10 that a link 490 is also pivotally mounted on the pin 456 carried by the lever 420. A slot 491, in the upper end of the link, embraces a pin 492 on the outer end of an arm 493 which is rigidly secured to shaft 324. A suitable spring 494, tensioned between the pin 492 and a suitable stud on the frame plate, not shown, urges the arm 493 and shaft 324 to an operative position (clockwise from the position shown in FIG. 10 and counter-clockwise from the position shown in FIG. 6). When the lever 420 is in the inoperative position shown in FIG. 10, it pulls the link 490 downwardly, thereby rendering the feed pawl 320 inoperative. The slot 491 in link 490 permits the rocking of the feed pawl 320 to an inoperative position at the end of each ordinal operation, by means which will shortly be described, although the control lever 420 remains in its rocked position until the multiplication operation is completed. However, for the moment it can be noted that the rocking of control lever 420 releases link 490 and permits the rocking of the shaft 324 under the force of spring 494, so that the check pawl 323 and feed pawl 320 are rendered operative. It will be recalled that the feed pawl is cyclically operated with each machine cycle, as it is connected to the constantly rotating drive shaft 107. Normally, however, the feed pawl 320 is rocked away from engagement with the rack 311 of segment 301 by the check pawl 323, so that the lifting of link 490 permits the enablement of operation of the feed pawl and the step-by-step rocking of the aligned segment 301 to the "0" position.

When the segment reaches the "0" position, it engages ear 326 on the forward end of the shift control lever 327 which is pivoted on a stub shaft 501. The rocking of this lever operates a mechanism which is effective to return the digitation control shaft 118 and the gate 116 to neutral

position, to disable the operation of the segment feed pawl 320, and to enable a shift of the multiplier carriage 290 and the accumulator carriage 51 for a single and simultaneous ordinal shift to the right. The mechanism for this purpose will now be described. In the conventional multiplier mechanism, the lever 327 is a single member, but in my preferred form of construction it is made in two sections, as shown in FIGS. 9 and 12, including the main lever member 327 and a forward section, or live tip, 502 which carries the ear 326. The two sections 327 and 502 are connected by a suitable pin-and-slot mounting comprising pins 500 on lever 327 engaging slots 503 in live tip 502. The forward section is urged forwardly so as to engage the segments 301 by a spring 504 tensioned between a projection 505 (see FIG. 12) on the forward part, or resilient tip, 502 and one of the pins 500. Thus, normally, the lever 502, 327 will be rocked by the return of a segment 301 to its "0" position, but this lever can be disabled to prevent operation from restoration of the segments by moving the forward portion 502 rearwardly against the force of spring 504.

The lever 327, at its rearward end, is provided with a pin 510 (FIGS. 6 and 9) which overlies portions of the two control links 480 and 481. Thus, one effect of the rocking of the lever 327, 502 is to return whichever link 480 or 481 is in operative position to a disengaged position. This is possible for, as will be explained hereafter, the positioning of these control links is through springs which permit the members to yield even though the control keys are latched in a depressed position.

A link 515 (FIG. 9) is mounted on the rear end of the lever 327, and, at its lower end, supports a hook member 516, one end of which is pivotally mounted on an arm 517. The arm 517 is rotatably mounted on the transverse shift pawl positioning shaft 518, and extends upwardly to an elevation lying in the path of travel of a pin 519 on the cam 468, when the latter is translated to its effective position. Thus, when the cam 468 is shifted to its effective position, it rocks the arm 517 idly with each cycle of operation, thereby reciprocating the hook 516. This operation is an idle one, as the hook 516 is normally in its elevated, or ineffective, position. However, when the lever 327, 502 is rocked (to the counter-clockwise position shown in FIG. 9), the hook member 516 is dropped, so that the hook portion thereof engages a stud 520 on a latch member 521 which is rotatably mounted on a transverse shaft 522. The latch 521 has a shoulder 523 which normally engages a transversely formed portion of an arm 530. Normally the arm 530 is latched in its raised, ineffective position by the latch member 521, but the reciprocation of the hook 516, when the latter is in its lowered position, pulls the latch member from underneath the arm 530, thereby permitting the arm 530 to be rocked downwardly (counter-clockwise in FIG. 9) by a strong spring, not shown. The dropping of the arm 530 is effective to centralize the digitation control shaft 118, as the rearward end of the arm 530 is connected to a link 531, which, in turn, is pivotally connected to a bellcrank centralizer 532 provided with a slot 533 that is adapted to engage the pin 485 on the lower end of the control lever 486, thereby locking it in the neutral position.

The spring-operated arm 530 is pinned to, or otherwise rigidly secured on, the shaft 518, so that the rocking of the arm is also effective to rock the shaft 518. This rocking of the shaft 518 controls the disabling of the segment feed pawl 320, the enablement of the right shift of the multiplier carriage 290, and enablement of the right shift of the accumulator carriage 51, as will now be described.

An arm 540 (FIG. 9) is likewise rigidly mounted on the shaft 518, so that it is rocked (counter-clockwise in this figure) when the arm 530 is released. This arm 540 is provided with a pin 541 which is embraced within a slot 542 of a link 543. The link 543 is pivotally connected to an arm 544 rigidly mounted on the shaft 324 at a point intermediate the frame plate 82 and the control plate 86, i.e., between arm 493 (FIG. 10) and pawl 323

(FIG. 6). Thus, the shaft 324 is rocked to its blocking position (counter-clockwise in FIG. 9 and clockwise in FIG. 6) to disable the feed pawl 320 by either the restoration of control lever 420 to the inoperative position shown in FIG. 10, or by the unlatching of arm 530 as a result of the rocking of shift control arm 327.

The rocking of the shaft 518 is also operative to cause the multiplier carriage 290 to be shifted one order to the right. It will be recalled that the multiplier carriage 290 is shifted by means of a shift pawl 335 (see FIG. 6), which engages, during the shifting operation, the teeth of rack 296 on the multiplier carriage. The shift pawl is continuously operated, as it is mounted on the constantly driven shaft 337. However, normally, the feed tooth on the ratchet arm, or pawl, 335 lies below the plane of the rack 296 so as to disable the shifting of the carriage. However, the shift pawl is lifted into the plane of the rack 296 by means of the arm 339 rigidly mounted on the shaft 518, as previously mentioned. Thus the rocking of shaft 518 rocks the arm 339 (clockwise from the position shown in FIG. 6) into the plane of the feed rack 296, and is therefore effective to initiate shifting on the multiplier carriage 290.

The rocking of the shaft 518 is also effective to initiate a single shift of the carriage 51 a single step to the right, as is fully explained in said patents to Friden Nos. 2,371,752 and 2,399,917, previously mentioned. The shaft 518 extends entirely across the machine, its right end being journaled in the right frame plate 81, as shown in FIG. 4. Adjacent its right end it carries a collar 551 that is axially shiftable but nonrotatably mounted on the shaft. The collar 551 is biased toward the left by a suitable compression spring 552 encompassing the collar and shaft. An arm 550 is securely mounted on the collar 551, and carries a pin 554. The assembly of the collar and arm is held in the right-hand position (shown in FIG. 4) by a flag, or bail, 553 which is mounted on the shaft 518 and extends to the left to a point where the tip of the flag is engaged by the carriage shift rack 296 whenever the carriage is in its home or its first adjusted position. An arm 555 is rotatably mounted on the shaft 518, to the left of the arm 550 a distance equivalent to two steps of the multiplier carriage, so that the arm 555 is engaged by the pin 554 whenever the collar and arm are permitted to shift to the left two steps under the bias of spring 552. The arm 555, in turn, carries a pin 556, which engages an arm 557 carrying a pin 558 engaging the front end of the right shift clutch bar 161. Thus the rocking of the shaft 518, when the multiplier carriage is in the second, or higher, ordinal position, operates the right shift control rod 161 to cause a right shift of the carriage.

As the multiplier carriage 290 shifts one step to the right as a result of rocking of shaft 518, the shift control arm 327, 502 and the ear 326 on the forward end thereof, is enabled to drop if the newly aligned segment 301 registers a value other than "0." Dropping of the sensing ear 326 lifts the hook 516, thereby enabling the resetting of the arm 530 and shaft 518 in their normal positions by means of the pin 519 (see FIG. 9) on cam 468 engaging the upper end of arm 540 (which is fast on shaft 518). The rocking of arm 540 and shaft 518, releases link 543 to enable shaft 324 to rock to operative position and thus enable the operation of the feed pawl 320. The return of shaft 518 to its normal latched position disables the carriage shift clutch 165 by rocking carriage shift arm 550 and thereby releasing arms 555 and 557, whereby spring 162 forces clutch control rod 161 to its inoperative position; and also disables the multiplier carriage shifting mechanism by rocking the arm 339 (counter-clockwise in FIG. 6), thereby permitting spring 338 to force the pawl 335 to its inoperative position. Thus the machine is enabled to carry forward a multiplying operation in the newly aligned order. These repetitive cycles in the various order continue until the multiplier car-

riage reaches its extreme right-hand position, which is a step beyond its normal, inactive, position.

The depression of the multiplier key 72 is also operative to set the digitation control mechanism for additive operation. The mechanism for this purpose is shown particularly in FIGS. 7 and 9. It will be seen in FIG. 7, that a bent arm 560 of a bail 561 carries a roller 562 that underlies the key stem 72. The bail 561 is rotatably mounted on the shaft 441, previously mentioned. Thus the depression of the key 72 rocks the arm and bail (clockwise in FIG. 7 and counter-clockwise in FIG. 9). The bail 561 has an integral arm 563 (FIG. 9), which arm supports the forward end of a long link 564. The rear end of the link 564 is supported by a bellcrank 565, pivotally mounted on a transverse shaft 566 adjacent the rear of the machine. The forward arm of the bellcrank 565 is pivotally connected to a depending link 567 hanging from an additive control arm 568 pivotally mounted on a transverse shaft 569. The rearward end of the arm 568 is provided with an aperture, or spring seat, in which is inserted a spring 570, the other end of which is seated on a stud 571 on the additive control link 480. Thus the depression of the key 72 rocks the bail 561 (clockwise in FIG. 7 and counter-clockwise in FIG. 9), thereby pulling the link 564 forwardly to rock bellcrank 565 and lift the arm 568. The lifting of the arm 568 (by means of spring 570), resiliently biases the additive control link 480 upwardly so that its shoulder 482 is adapted to engage the pin 484 and, upon operation of the cam follower 476, as heretofore described, to power-set the digitation control mechanism including the shaft 118.

The depression of the accumulate multiply key 73 is effective to initiate the same sequence of operations described in connection with the multiply key 72, except that the clearing mechanism is disabled so as to permit the accumulation of the products in the accumulator register 52. For this purpose the accumulate multiply key 73 is provided with a pin 580 (FIGS. 9 and 10) which is embraced within a slot 581 in the forward end of a long lever 582. The lever 582 is pivoted at approximately the middle of the machine on a pivot screw 583, and extends rearwardly therefrom to a point adjacent the end of the control lever 568. The rear end of the lever 582 is provided with a suitable pin, or roller, 584 embraced within a slot 585 in the rear end of the lever 568. By this means, the control lever 568 is lifted by the depression of the accumulate multiply key 73, as well as by the depression of multiply key 72 as previously described. It will be recalled that the lifting of the lever 568 causes the resilient positioning of the additive control link 480 in an operative position. Thus the machine is conditioned for additive operation.

An operating arm 590 (FIG. 10) is also pivotally mounted on the screw 583, and is provided with a pin 591 at its forward end which underlies the lever 582. Thus the rocking of the lever 582 is also effective to cause rocking (clockwise in FIG. 10) of the lever 590. The lever 590 is provided with a downwardly projecting arm 592, the lower end of which abuts against a pin 593 carried by a formed arm 594 rigidly mounted on the shaft 371. It will be recalled that the multiply key 72 also rocks shaft 371 (see FIG. 7) and that this shaft controls the program of shifting the carriage, and clearing the register, as previously described. Thus, the rocking of the setting lever 590 is effective to rock the shaft 371 (counter-clockwise in FIG. 10 or clockwise in FIG. 7) to cause the initiation of machine operation and to program the machine for repeated shifts to the right to the extreme end position. The operation so initiated follows the cycles of operation described in connection with the operation of the multiply key 72, except that the clearing mechanism clutch is disabled by means which will now be described.

The lever 590 (FIG. 10) is also provided with a pin 595 which is embraced within the slot 596 of an upwardly extending link 597. Link 597 is pivotally mounted on an arm 598 which is rigidly mounted on a shaft 599. This assembly is resiliently biased upwardly against the pin 595 by a suitable spring 600. Shaft 599 extends from the control plate 86 to the left side frame plate 82, as shown in FIG. 7. On its right-hand end, the shaft 599 carries an arm 601 that is provided with a pin 602, as shown. The pin 602 abuts against a bellcrank arm 603 integral with the pusher link 239 that operates the clearing clutch rod 240. Thus, the depression of the lever 590 rocks the shaft 599 (counter-clockwise in FIG. 10 and clockwise in FIG. 7) to rock the pusher link 239 (counter-clockwise in FIG. 7) to disengage it from the clutch push rod 240. This disables a clear clutch operation. With this exception of disabling the clear clutch operation, the program initiated by the depression of the accumulate multiply key 73 is the same as that initiated by depression of the multiply key 72.

The lower end of the key stem of the negative multiply key 74 (FIGS. 9 and 10) is provided with a pin 610 which is embraced within a slot 611 formed in the forward end of a control lever 612 which conventionally lies between the accumulate multiply lever 590 and the auxiliary, or control, plate 86. This lever is also pivoted on stud 583, and also overlies the pin 591 on the setting lever 590. Thus, depression of the negative multiply key 74 is also operative to rock the lever 590, which, in turn, initiates the multiplication operation by the rocking of the shaft 371 and also disables the clear clutch by rocking shaft 599 (both of which have been previously described). The lever 612 also extends rearwardly of the pivot point 583 and is provided with a stud 613 (see FIG. 6) which serves as a spring seat for the tension spring 614, the lower end of which is connected to the subtractive setting link 481. By this means, the rocking of the lever 612 resiliently biases the subtractive setting link 481 upwardly, so that its shoulder will engage the pin 485 on the lever 486 when the power setting mechanism, which includes the cam 468 and follower 476, is operated.

II. STORAGE REGISTER MULTIPLYING MECHANISM

The mechanism of the present invention is particularly designed to cause a multiplying operation in which the multiplier value is taken from a storage register, such as the storage dials 75 (FIG. 1) arranged across the front of the frame, and preferably in front of the square root keys 69. These dials preferably are viewable through suitable windows 76 and preferably will be aligned with value keys 60. The values registered in the dials 75, and utilized as a multiplier factor, may be secured by setting the multiplier value into the keyboard keys 60 and then directly transmitting it into the register dials 75, as described in my Patent No. 2,714,989, issued August 9, 1955; or may be set in the multiplier dials by an interregister transfer from the inboard accumulator dials 52 as described in the last-mentioned patent or in Patent 2,909,320 of Arthur Malavazos, issued October 20, 1959, or my copending application S.N. 486,323, filed February 7, 1955. It should be noted that the present invention is concerned primarily with a multiplying mechanism which utilizes the factor registered in the storage dials 75, and is only incidentally concerned with the mechanism by which a value is set into those dials. In this connection, it can be mentioned that the dials 75 can correspond to the dials 237 of my Patent No. 2,714,989, or the dials 601 of the Malavazos application just mentioned. It will be understood that the multiplicand value will be set into the keyboard keys 60 and retained there until the multiplication operation is completed. It will also be understood by those skilled in the art that this mechanism is not limited to use in the Friden type machine,

but can be used in connection with any calculating machine used differentially set selection bars or slides.

The mechanism of the present invention is primarily designed to perform a multiplication operation using 5 the value in the keyboard as the multiplicand and the value in the storage dials 75 as the multiplier. As the multiplier value can be entered from the keyboard, if desired, the mechanism affords a convenient means for multiplying a value by itself, i.e., squaring the keyboard value. In such an operation, the value in the keyboard 10 is transmitted into the register dials 75 and is also retained in the keyboard as a multiplicand. In a secondary form of the present invention, the mechanism can be used as a squaring mechanism for the conventional machine, 15 utilizing the multiplying mechanisms of the Friden patents previously mentioned. In the latter event, the mechanism of the present invention would necessarily be an auxiliary control to the conventional "Friden" machine described in said patents, while in the former case, 20 the multiplying mechanism could be substituted for the conventional multiplying mechanism, if desired. It has been mentioned previously that the invention, as illustrated herein, is added to a "Friden" multiplying machine of conventional construction, although it will be 25 obvious to those skilled in the art that the conventional multiplying mechanism could be discarded and the present invention used in its place.

In connection with the present invention, I prefer to use the conventional multiplication control keys of the 30 "Friden" machine, such as the multiplication key 72, accumulate multiplication key 73, and the negative multiplication key 74, to initiate similar types of multiplying operations. These keys will set the digitational control gate as described in connection with the conventional 35 multiplier mechanism, and will operate the shifting and clearing mechanism in the same programs as in conventional multiplication. However, means will be provided to disable the rocking of the conventional multiplier control shaft 324, so that the feed of the multiplier control segments will be disabled throughout the operation; and to disable the shift control arm 339 and the shift pawl 335, so that the multiplier carriage shift will also be disabled. In my preferred form, however, I will utilize the rocking of the shift control lever 327, 502 to terminate an operation in one order of the machine, to 40 temporarily centralize the digitation control shaft 118, to cause a shifting of the register carriage a single step toward the right, and to reinitiate multiplication operation under the control of the storage dial 75 of the next higher order.

Needless to say, in the multiplication operation of the present invention, operation is controlled by a value set in the main keyboard 60 and transferred directly into the storage dials 75, or by the transfer of a value from the 55 accumulator dials 52 into the storage dials 75, rather than values set into the conventional multiplier keyboard 70. In order to accomplish this purpose, I provide auxiliary slides associated with each order of the machine, which slides are set forwardly a single step with each cycle of 60 machine operation until forward movement is blocked by the auxiliary slide engaging the stopping face of a step cam, or in the second embodiment, until movement is blocked by the auxiliary slide engaging the depressed key in that order. The engagement of the auxiliary slide 65 with the cam stop, or with the depressed key, as the case may be, results in rocking the shift control arm 327 to thereby initiate the conventional program, including centralizing the digitation control shaft 118 and initiating a single shift of the carriage to the right. The auxiliary 70 slide, the method for feeding it forwardly step-by-step with each cycle of machine operation, and the means for selecting the order in which the slide is to be fed, is strikingly similar to that utilized in my joint Patent No. 2,736,494, previously mentioned, for the extraction of 75 square root. As a matter of fact, in its preferred form,

my present invention can be associated with the mechanism of that patent so that a single machine will be capable of extracting the square root and either multiplying or squaring factors, for the most part utilizing the same feed mechanisms shown and described in that patent.

1. Method of operation

It has just been indicated that the multiplication of the present invention is accomplished by use of an auxiliary slide associated with each order to the keyboard, an operative one of which will be fed forwardly in single steps, or increments, with each cycle of machine operation until such movement is blocked by the engagement of such slide with a value, or step, cam, the angular position of which is representative of the value standing in the dials 75; or, in the mechanism designed particularly for squaring shown in the second embodiment, by engagement with the depressed key stem of that order. It is believed that the mechanism of my invention will be more readily understood if first the theory of operation is fully explained.

The inventive concept in my invention lies in providing an auxiliary slide associated with the selection slides of each order, the auxiliary slide being fed forwardly a single step with each cycle of operation, including, in the lowest order, the cycle in which the override pawl is operated at the end of the leftward shifting of the carriage, and, in the higher orders, each shift cycle. Such movement of the auxiliary slide continues until it is blocked by a value cam, or, in the second embodiment, by a depressed value key in that order. It can be mentioned here that in the preferred form of my invention, I provide one of these auxiliary slides for each order of the keyboard, but it will be obvious that if it is desired to limit multiplying to a portion of the keyboard, it will be necessary only to provide such slides in the selected orders. In my invention the auxiliary slides are activated order-by-order from right to left, by means of a cam shaft 850, similar in form and mode of operation to the cam shaft of the square root patent, No. 2,736,494 above-mentioned.

The auxiliary slides herein mentioned are similar to the auxiliary slides utilized in the square root patent previously mentioned. These slides are fed a single step forwardly with each machine cycle a number of steps, or increments, determined by the value standing in the cam (or key) of that order. If, for example, a value of "5" stands in the multiplier dial 75 of a particular order, five forward steps will cause the auxiliary slide to engage the "5" face, or stop, on the cam. However, such mere engagement normally will not provide sufficient force to operate the shift control arm 327, which force can best be secured when movement of the slide is blocked by the cam, i.e., in the next, or sixth, feed. For this reason it is necessary to feed the auxiliary slide one step, in each order, prior to the initiation of digitation in that order. This preliminary feed can readily be secured by giving the lowest order slide its first step of movement during the operation of the override pawl, and by giving the higher orders their first step of movement during the shift of the carriage into the associated ordinal position. By this means, the slide is given a single step prior to digitation in the particular order, so that the slide will just touch the value cam after a number of cycles of digitation equal to one less than the value standing in the value cam or the value of the depressed key (after the fourth digitation cycle in the above example). Then in the next machine cycle, the digitation mechanism, still being in operative position, enters the value an additional time and during this cycle the auxiliary slide will again start to move. However, during this cycle, operation, will be blocked by the firm engagement of the slide with the respective value face, or block, on the cam. This will create a back-pressure sufficient to release the shift control arm 327, but the digitation cycle must be completed

due to the conventional interlocks in the machine. The back-pressure created by this blocking of the feed of the slide then causes operation of the shift control arm 327, which disables the digitation control links 480 or 481 and initiates a single shift of the carriage, as previously described.

It is necessary to provide a mechanism associated with the auxiliary slides and the means for feeding them forwardly, which is effective to select one, and only one, slide for operation. This can preferably be done by a series of ordinarily arranged cams on a single cam shaft 850, similar to the cam shaft of the square root machine above referred to, but working in the opposite direction. In square root the cams are effective to select ordinal operation beginning with the highest order and progressively moving order-by-order to the right. In a multiplying operation, on the other hand, it is preferable to work from the lowest order toward the highest. I have adapted the mechanism of my machine to work in conjunction with the square root mechanism of the square root patent above-mentioned, and for this purpose provide an additional cam shaft and ordinarily arranged cams thereon while using the auxiliary slide and auxiliary slide feed of the square root machine.

At the end of the multiplying operation, I prefer to operate the keyboard clearing mechanism and the mechanism which has retained the auxiliary slides in their adjusted position so that the machine is cleared for another operation. It will be obvious that if the auxiliary slides were held in their adjusted positions, after the end of a multiplying operation, the attempt to initiate a second multiplication operation would cause misoperation or jamming of the machine. Therefore, as a safety factor only, it is preferred that the last cycle of machine operation be effective to clear the keyboard and to reset the auxiliary slides.

In connection with my invention, it will also be obvious that as the auxiliary slides are fed forwardly with each cycle of machine operation, it will be necessary in the second embodiment, to provide a zero latch which will block these slides against operation in all orders in which no value has been inserted. This can be accomplished by a variety of means, but I prefer to provide a mechanism which will be operated by the override pawl to insert a block in all orders in which no value has been inserted, which block will be effective to prevent any feed of the auxiliary slides.

2. Conditioning key

Preferably the machine of my invention will be provided with a conditioning, or control key, such as key 625 (FIG. 1) marked "REG MULT," which is an abbreviation for "Register Multiplier." This key can be moved forwardly from the position shown in FIGS. 1 and 11, and latched in the forward, or operative, position. The movement of the key 625 to its forward position, conditions the multiplying mechanism of my invention by disabling the normal multiplying operations of feeding the segment feed pawl 320 (FIG. 6) and multiplier carriage shift pawl 335; conditions the multiplier shift control arm 327 for operation by means other than the return of a segment 301 to its "0" position and sets a control mechanism which will be operative, when one of the multiplier control keys is depressed, to feed an auxiliary slide forwardly a single step with each cycle of machine operation, order-by-order, from right to left, until the movement of the auxiliary slide is blocked by engaging the stop shoulder of a value cam, or, in the second embodiment, one of the depressed keys 60. These various mechanisms, including the key 625, will now be described in detail.

As shown in FIG. 11, the conditioning key 625 is preferably mounted on a bellcrank member 626 which is pivotally mounted on a setting slide 627 by any suitable means, such as screw stud 628. The slide 627 is mounted for substantially longitudinal movement along

the auxiliary frame plate 86, such as by a pair of slots 639 in the slide engaging a pair of studs 629 riveted on, or otherwise rigidly secured to, the frame plate. The bellcrank member 626 is likewise provided with a slot 630 which registers with the forward slot 639 in the slide, both slots embracing the forward pin 629. The slot 630 of the bellcrank 626 is provided with an offset portion, or notch, 631, whereby the bellcrank 626 can be rocked (counter-clockwise in FIG. 11) about its pivot 628 whenever the slide 627 and bellcrank 626 are in their forward positions. Such rocking of the bellcrank latches the key 625 and slide 627 in the forward, or operative, position by virtue of the notch 631 engaging the forward stud 629. A spring 632, tensioned between a stud 633 on the rear end of the bellcrank and a stud 634 on an arm 635 rigidly mounted on the slide 627, resiliently biases the key 625 and bellcrank 626 into the detented position (counter-clockwise around the pivot 628) when the assembly is moved to the forward, or operative, position.

Movement of the slide 627 to the forward, or operative, position, is effective to: (a) retract the resiliently projected tip 502 of the shift control arm 327; (b) disable the multiplier keyboard; (c) disable operation of the multiplier segment feed pawl 320; (d) disable operation of multiplier carriage shift pawl 335; (e) conditions the machine for a right shift upon every operation of the shift control arm 327, irrespective of the position of the multiplier carriage 290; and (f) conditions the multiplication mechanism of my invention for operation, under control of the conventional keys 72, 73 or 74.

(a) *Retract projecting tip of shift control arms*

The forward translation of the slide 627 is operative to retract the normally projected tip 502 of the shift control arm 327 in order to disable operation of that arm by the multiplier segments 301. In the preferred form of my invention I utilize the shift control arm 327 to control shifting of the register carriage 51 from order-to-order, so that I prefer to have the rear portion of the arm 327 operate in a conventional manner, but from different controls. Therefore, it is necessary to provide the shift control arm 327 with the resilient projecting tip 502, so that it can be retracted and thus prevent operation thereof by the upper ends of the multiplier segments 301 or the block 328 which conventionally is carried by the multiplier frame plate 292 and lies to the left of the highest order segment 301, and to enable operation of the arm 327 under other controls, regardless of the positions of multiplier segments 301. This purpose can be secured simply and easily by providing the arm 327 with the live, or resiliently projecting, tip 502, which, when retracted, prevents the segments 301 from engaging the arm, for it is possible that the multiplier carriage 290 may be out of its inoperative position (as when a repeat multiplier factor is locked therein). It will be recalled that it is necessary for the forward end of the arm 327 to rock upwardly (clockwise in FIG. 6 and counter-clockwise in FIG. 9) to initiate a shift, and to rock in the opposite direction for digitation in the particular order. Thus the retracting of this yieldable tip enables operation of the arm 327 by my new mechanism, regardless of the position or condition of the multiplier carriage.

I prefer to utilize the simple retracting mechanism shown in FIGS. 11 and 12, which includes a stud 636 riveted on, or otherwise rigidly secured to, the rear end of the slide 627. Cooperating with the stud 636 is a bent, or cam, arm 645 which is rigidly mounted on a shaft 646 journaled in the left side auxiliary frame plate 86. The shaft 646 carries a second arm 647 lying immediately to the right of the frame plate 86, as shown in FIG. 12. The downwardly projecting arm 647 engages a roller 648 mounted on the left end of an arm 649 projecting to the left from the yieldable tip 502 of the arm 327. Thus the translation of the slide 627 to

its effective position (forwardly in FIG. 11) rocks the arm 645 and the shaft 646 (clockwise in this figure), thereby rocking the depending arm 647 rearwardly. The rocking of the arm 647 pushes the roller and its arms 649 rearwardly, thereby retracting the forward tip 502 of control arm 327 against the force of its spring 504. This effectively disables the operation of the shift control arm 327 by the multiplier mechanism and thus permits control of the shift control arm solely from the mechanism of the present invention.

(b) *Disable multiplier keyboard*

A second effect of the forward translation of the slide 627 is to disable the multiplier keyboard, that is, to lock it against operation. This interlock is not essential as the multiplier mechanism is disabled, so that a value can stand therein, such as on repeat multiplication, without effecting operation of the present multiplying mechanism. However, it is preferred that the depression of the multiplier value keys 70 be blocked when the conditioning key 625 is in its operative position, for then an operator will be warned that the machine is conditioned for multiplication from the storage register dials 75 if he attempts to insert a multiplier value into the machine. Such blocking of operation of the multiplier keyboard is readily accomplished by the movement of the slide 627. As shown in FIG. 11, the slide 627 carries a downwardly projecting arm 635 which is mounted on the slide by a pair of studs (one of which can be the pivot stud 628) in order to prevent rocking of the arm 635 with respect to the slide. The lower end of the slide 635 is provided with a slot 638 which embraces a pin 655 on a link 656. The rear end of the link 656 is supported by a two-armed lever 657, to which it is pivotally connected as by means of a long pin 658. The lever 657 is pivotally mounted on the left-hand auxiliary plate 86 by any suitable means, such as stud 659, and the upper end thereof is urged rearwardly (counter-clockwise in FIG. 11) by a suitable spring 660. The forward end of the link 656 is pivotally supported by an arm 661 which is rigidly secured to a short shaft 662. The shaft 662 also carries an arm 663 (shown in FIG. 6), the rocking of the shaft (clockwise in FIG. 11, counter-clockwise in FIG. 6) lifting the rear end of the arm 663 to engage the conventional interlock lever 664 which locks the multiplier value keys against operation.

(c) *Disable multiplier feed pawl*

A further effect of the forward translation of the slide 627 is to disable the operation of the multiplier segment feed pawl 320, previously described. A simple means for accomplishing this purpose is shown in FIG. 11, and comprises a link 670, the forward end of which is supported by the pin 658 on link 656. The motion required of link 670 is less than that required by link 656, so preferably link 670 is provided with an elongated slot 671 which provides a lost motion connection with the pin 658. The rear end of the link 670 is pivotally mounted on a depending arm 672 by any suitable means, such as stud 673. The arm 672 is rockably mounted on the auxiliary plate 86 by any suitable means, such as by screw 674. The lower end of the arm 672 is provided with a locking edge, or face, 675 which normally lies immediately to the rear of the pin 492 which forms the connection between the link 490 and the arm 493. It will be recalled that the rocking of arm 493 (clockwise in FIGS. 10 and 11) is effective to enable operation of the segment feed pawl 320 step-by-step. It is necessary to disable this feed pawl, so that if a repeat multiplier factor is set in the multiplier carriage, the feed pawl will be ineffective to change it during operation of the squaring mechanism. This is most readily accomplished by blocking operation of the arm 493, and with it the shaft 324 and disabling pawl 323 (FIG. 6). It is obvious this operation does not disable the link 490 (FIG. 10) and

levers 458 and 420 which are connected to the link 490. In this connection it should be remembered that the mechanism of FIG. 11 is superimposed upon that shown in FIG. 10, so that the rocking of the arm 672 will move the lower blocking end 675 thereof over the pin 492, and block operation of the parts mentioned.

(d) *Disable multiplier carriage shift pawl*

The lower end of the lever 657 abuts against a pin, or stud, 680 mounted in the upper end of an arm 681 that is rigidly secured to a transverse shaft 682. Thus the manipulation of slide 627 to its forward, or effective, position, rocks the two-armed lever 657 (clockwise in FIG. 11), and the latter, in turn, rocks the arm 681 and shaft 682 in the opposite direction. The shaft 682 extends to the right from the auxiliary frame plate 86 to a bracket 683 (see FIG. 4) located adjacent the right frame plate 81. The shaft 682, among other things, carries an arm 684 (see FIG. 6) located in a plane adjacent the hub 336 which mounts the multiplier carriage feed pawl 335. An ear, or bracket 685 is integral on the free end of the arm 684, which ear underlies the hub 336. The movement of the ear 685 from the rocking of shaft 682 is sufficient to lift the feed pawl 335 above the plane of the rack 296 of the multiplier carriage 290, so that the pawl cannot engage the rack. This condition is maintained as long as the multiplication conditioning key 625 is in its effective position, and therefore disables the operation of the multiplier carriage shifting mechanism throughout all multiplication operations under control of key 625. It should be noted that shaft 518 is free to rock from operation of the shift control lever 327, 502, but that such rocking will not effect a multiplier carriage shift, for the pawl is latched in a position above that to which it is lifted by pin 340.

(e) *Condition the machine for right shift on each operation of the shift control arm*

It will be recalled that in conventional multiplication, when the multiplier segments 301 return to their normal, or "0," position, the shift control arm 327 is rocked thereby. The rocking of the shift control arm, whether caused by the mechanism previously described, or by the new mechanism to be described hereafter, controls the unlatching of the arm 530 (FIG. 9) and shaft 518. Shaft 518 carries the shift control arm 550 (FIG. 4) which is nonrotatably but slidably mounted thereon. When the multiplier carriage is in its normal position, to the right of the feed pawl 320, this arm is pushed to the right by the bail, or flag, 553 shown in FIG. 4, so as to disable the connection between the arm 550 and the right shift control mechanism. It is only when the carriage has been shifted two orders to the left that this arm shifts into a position to become operative upon the rocking of shaft 518. This disabling of the right shift is required in order that rocking of the shaft will not cause a shifting when the multiplier carriage has not been shifted out of its home position by the entry of values into it, or when only one value has been entered (which is an operation sometimes desired).

However, in the preferred form of my invention, it is necessary that the carriage be shifted with each operation of the shift control arm 327 and shaft 518, and for this purpose I prefer to use a mechanism controlled by the rocking of the shaft 682. As shown in FIG. 4, the right end of shaft 682 carries an arm 700 rigidly secured thereto by any suitable means, such as a pin or set screw, not shown. This arm 700 extends rearwardly and its free, or distal, end overlies the lower arm of a bellcrank member 701 which is pivotally mounted, as by pivot stud 703, on a collar 702 rigidly secured to the shaft 518. Whenever the shaft 682 is rocked (counter-clockwise in FIG. 11), the arm 700 rocks the bellcrank 701 (clockwise in FIG. 4), so that a nose 704 on the upper end of the bellcrank lies in front of the arm 557 which is pivotal-

ly mounted on the shaft 518. It will be recalled that this arm carries a long pin, or stud, 558 which lies in front of the clutch control rod 161. In normal multiplication operations, the arm 557 is operated by the arm 550, which is rigidly mounted on the collar 551 that shifts to the left two spaces as the multiplier carriage 290 is shifted to the left with the entry of the first two values thereto. Thus the arm 557 is operated in conventional multiplying operations by the arm 550, and in a register multiplying operation is operated by the bellcrank 701. The bellcrank is first rocked (clockwise in FIG. 4), so that its nose 704 lies in front of the arm 557 and then, upon operation of the shift control arm 327 and the consequent rocking of shaft 518, is rocked rearwardly to push the clutch control rod 161 to its rearward, or effective, position. Thus the rocking of the shaft 682, by the setting of the conditioning key 625, is effective, among other things, to condition the machine for a right shift of the accumulator carriage 51, whenever the shaft 518 is rocked as a result of the rocking of the shift control arm 327.

It is thus seen that the setting of the conditioning key 625 to its forward, or operative, position has been effective to first disable certain normal multiplication operations which would interfere with the present program of multiplication operations: by retracting the projected tip of the shift control arm 327, so that the operation of this arm will not be affected by any setting of a multiplier control segment 301; by placing blocking lever 672 over pin 492, and thereby blocking rotation of shaft 324 and operation of the multiplier segment feed pawl 320; and by rocking shaft 682 to lift the multiplier carriage shift pawl 335 above the plane of the shift rack on the multiplier carriage. The operation of conditioning key 625 also conditions the machine for a right shift of the carriage upon each operation of the shift control shaft 518, regardless of the position of the multiplier carriage. Finally, the setting of the conditioning key 625 to its operative position conditions the mechanism of my invention for operation, as will next be described. For the moment, however, it can be noted that when the machine is so conditioned, operation of any of the multiplier control keys 72, 73 or 74, initiates a multiplication operation in which the value set in the storage register dials 75 is used as a multiplier factor.

(f) *Conditioning the register multiplier feed mechanism*

Another effect of the movement of the squaring key 625 to its forward, or effective, position is to condition the present multiplying mechanism for operation. It can be mentioned at this point that the operation of the present multiplying mechanism is under the control of the cam shaft 850 (the left end of which is seen in FIG. 11), the shaft being resiliently biased toward the right side of the machine by a spring, as will hereinafter be described. This shaft is latched in the right-hand, ineffective, position to which it is biased in all operations except multiplication from the register dials 75; and in the present multiplying operations, is shifted to the left by the operation of the override pawl at the termination of the leftward shifting of the carriage to the extreme end position. The leftward movement of the shaft 850 normally is blocked by an arm 720 (shown in FIG. 12). The arm is pivoted on a screw stud 721 and is operated from the operation of the override pawl, by a yieldable linkage, as will hereinafter be described. At this point, however, it can be noted that the lower end of the lever 720 is provided with a stud 722, which, in the normal, or rearward, position of the slide 627, engages a tail 637 on the rear end of the slide 627, thereby preventing operation of the blocking lever 720 and consequent unblocking of shaft 850, and hence operation of the present multiplying mechanism. When the slide is moved forwardly to condition the machine for a register multiplying operation, the tail 637 moves sufficiently forward to release the stud

722, whereupon the blocking arm, or lever, 720 can be operated.

3. Auxiliary slides

In the preferred form of my invention, I provide an auxiliary slide 730 lying immediately to the right of the selection bars of each order of the machine (see FIG. 15). The auxiliary slides 730 (FIGS. 2, 13 and 15) are slidably mounted in slots, not shown, in the crossbar member 83 and a comb 732 (FIG. 16) at the forward part of the selection mechanism. These slides are resiliently biased toward the rear to an inoperative position by any suitable means, such as a spring 734 tensioned between a spring seat on the comb 732 and a nose 733 projecting from the forward end of the slide. Each of these slides is provided with a nose, or shoulder, 731 adapted to engage a multiplier value cam 980 described in the next section.

It will be recalled that it has been mentioned that the mechanism of the present invention is designed particularly to use parts and mechanisms of the machine for the extraction of square root described in my joint Patent No. 2,736,494 previously mentioned. The second embodiment, which discloses a squaring mechanism as distinguished from a multiplying mechanism, is particularly adapted to be combined with that machine. However, where the present mechanism is designed for use in any multiplication operation, the auxiliary slide 730 is preferably modified so that the shoulder 731 will cooperate with the cam 980 rather than the ordinarily related selection slides 96, as in the square root machine. It can be noted that in the extraction of square root, the auxiliary slide 730 is moved forwardly by the machine step-by-step with each cycle of machine operation to progressively move the selection bars to the proper differential position for the extraction of square root. It is obvious that the ear 731 could not be used to both set the selection slide and to cooperate with the cam 980, for a value standing in the multiplier cam 980 might prevent proper operation of the square root mechanism, and conversely, a value standing in the selection mechanism, or keyboard, might interfere with multiplication operations. For this reason, it is preferred, insofar as the present invention relates to a multiplying mechanism which can be utilized for any type of multiplication operation, that this slide be disassociated from the square root mechanism; although it is obvious that means could be provided which would selectively control slide operation with one or the other, but not both, at the will of the operator.

The auxiliary slide 730 in the operative order is given a single step of forward movement with each cycle of machine operation by means of a rack 735 formed on the rear end of the slide, which rack meshes with a drive gear 750 which is given the necessary step operation, as will be described in the second succeeding section entitled "Slide Feeding Mechanism."

4. Multiplier control cam

A multiplier control cam suitable for the present invention is shown particularly in FIG. 16, which corresponds to FIG. 1 of my Patent No. 2,714,989 already mentioned. Each step cam 980 (there being one for each order), is mounted on a longitudinally extending shaft 981 (which corresponds to shaft 245 in said patent). The shaft 981 is journaled in the intermediate cross-frame member 83 and the front crossframe member 87. It is provided on its forward end with a gear 982, which, through idlers 983 and 984, is connected to a dial gear 985 which is attached to, or formed integral with, the multiplier dials 75. This train of gears 982, 983, 984 and 985 are preferably all of the same size, so that both the shaft 981 and the dial 75 will simultaneously make a complete revolution. Therefore, the angular position of the cam 980 and shaft 981 will always correspond to the value position of the dial 75.

The shaft 981 can be clutched to the square, or selec-

tion, shaft 100 by any suitable means, such as by driving clutch member 986, which is slidably but nonrotatably mounted on the forward end of square shaft 100, and a driven clutch member 987 formed on one end of a sleeve 5 rotatably mounted on the forward end of the shaft 100. This clutch assembly (corresponding to the parts 256 to 263, inclusive, of the patent above-mentioned), is controlled by the rocking of shaft 991, in order to selectively clutch the shaft 981 to the square shaft, as required by the operator. The sleeve 987 is connected to the associated shaft 981 by means of suitable gears 988 and 989, as explained in said patent. When the clutch members 986, 987 are engaged, any rotation of the square shaft 100 will drive shaft 981 and dial 75 the same amount. Thus a value set by a value key 60 can be run directly into the ordinarily aligned multiplier dial 75 in a single cycle of the machine operation, the value also being set into the accumulator dials 52 if the digitation control gate 116 is set to an operative position. Similarly, a value standing in the inboard register dials 52 can be run into the multiplier dials 75 by causing engagement of the clutch members 986, 987, moving the digitation control gate 116 forwardly (FIG. 2) so that the subtract gear 112 meshes with the accumulator dial gear 113, and 15 then clearing the dials 52, as was also fully explained in my aforesaid patent. Thus a value can be set directly into the multiplier dial 75 either from the keyboard or from the register, as desired.

The cam 980, as shown in FIG. 16, is preferably a cylindrical one, having ten equiangular spaced shoulders 990 differentially spaced longitudinally of the cam. These steps correspond to the values of "0" and "1" to "9," reading from back to front of the machine, and the longitudinal spacing corresponds to the incremental steps of movement of auxiliary slides 730 and the selection bars 96. These shoulders are associated with the nose 731 on the slide 730, the nose abutting the rear end of the cam, or the "0" face thereof, when the multiplier dial 75 stands at "0." Thus forward movement of a slide 730 will be blocked whenever the associated dial 75, and consequently cam 980, stand at "0." Any rotation of the dial 75 to the various values rotates the cam corresponding increments, and thereby permits the forward translation of the slide corresponding amounts until the ear 731 abuts one of the faces 990 of the cam. It will be recalled that the auxiliary slide 730 in the operative order is given a single step of forward movement with each cycle of machine operation, as will be described in the next section. This feed is continued until the ear 731 is blocked from further movement by engaging the faces, or steps, 990 of the cam 980—the back pressure created thereby being utilized to terminate the multiplication operation in the operative order, to cause the necessary shift of the carriage (which simultaneously shifts the multiplier control to the next higher order of the mechanism), and to again initiate a multiplication operation.

5. Slide feeding mechanism

It has been mentioned previously that the auxiliary slides 730 are fed, as required by the operation of my invention, by a feed gear 750 which meshes with a rack 735 on the auxiliary slide 730. In the preferred form of my invention I provide a drive assembly, shown particularly in FIG. 13, in each order of the machine. This mechanism is mounted in a frame, indicated generally by 751 (see also FIG. 15), which is provided with a plurality of separator plates 752 which also serve to strengthen and brace the frame. The drive gear 750 is preferably formed integral with a larger idler gear 753, the two gears being rotatably mounted on a transverse shaft 754 which extends across the control frame 751. The gears are held in properly spaced position on the shaft 754 by means of spacing collars 755 and 756.

A drive shaft 760 is mounted in the frame 751, preferably being square, as shown in FIG. 13. In each order

of the machine, a driving gear 761 is slidably mounted on the shaft and is normally biased to the right, out of mesh with the idler 753, by a suitable compression spring 762 compressed between the gear 760 and the separator plate 752 to the left thereof. It can be mentioned at this point that the shaft 760 is given a single step of rotational movement in all cycles of a multiplication operation, thereby rotating all of the gears 761 (which are slidably but non-rotatably mounted thereon). Normally, however, the gears 761 do not mesh with the gears 753, so that the rotation of the shaft 760 is ineffective to move the auxiliary slides 730, and can operate upon an idler and slide 730 only when a driving gear 761 is cammed to the left by means which will be described under the heading of "Order Selection Mechanism."

It can be mentioned at this point that the idler gear 753, and consequently the auxiliary slide 730, are held in each adjusted position by means of a detent bellcrank 770 (FIG. 13) pivotally mounted on a transverse shaft 771. The bellcrank 770 is provided with an ear 772 which normally latches behind a tooth of the idler gear 753, against which it is pressed by means of a torsion spring 773. The ear is so formed that it is cammed out of engagement with the idler when it is driven by the drive gear 761 (the idler being driven clockwise in FIG. 13) but blocks return movement of the idler. The detent bellcrank 770 is provided with a tail 774 which can be lifted by the clearing cam 1111, hereinafter described under the heading "Clearing Mechanism," to release all of the gears 753 and permit the auxiliary slides 730 to be returned to their normally inoperative position by their springs 734.

The means for feeding the drive shaft 760, a single increment of motion with each cycle of machine operation, is shown particularly in FIG. 17. The power for operating the feed shaft 760 is derived from a feed cam 780 mounted on the power shaft 107, immediately to the left of the left side frame plate 82. The cam is shown in FIG. 17 in its full-cycle position, the shaft 107 rotating counter-clockwise in this figure as indicated by the arrow. Associated with the cam 780 is a three-armed follower lever 781, pivotally mounted on the frame plate 82 by any suitable means, such as on a stud 784. This lever has a forwardly extending arm 782 carrying a roller 783 on its free, or distal, end, the roller being located so as to engage the periphery of the cam 780. The follower roller 783 is biased into engagement with the periphery of the cam 780, and the lever member 781 is biased in an operative direction (clockwise in FIG. 17) by means of a relatively strong spring 785 tensioned between the upper arm 786 of the three-armed lever and a suitable stud on the frame plate, not shown. Thus, when the follower member 781 is released for operation, the relatively strong spring 785 biases the follower member (in a clockwise direction in FIG. 17) into engagement with the periphery of cam 780. It is obvious, from the shape of the cam, that the follower member is permitted to rock (clockwise in FIG. 17) slightly before the 180° position of the shaft and cam, has completed its stroke in another 45° to 60°, and is restored to the full-cycle position at approximately the end of the cycle of operation.

The forward rocking of the upper arm 786 of the follower member is effective to rotate the shaft 760 a single step of movement. For this purpose the upper arm 786 carries a live pawl 790, which is pivotally mounted thereon by any suitable means, such as stud 791. The pawl 790 is resiliently biased to an effective position by a suitable spring 792 tensioned between studs on the arm 786 and the pawl 790. The forward end of the pawl is adapted to engage the teeth of a ratchet gear 793 mounted on the left end of the feed shaft 760. Thus the operation of the follower member 781, from the force of strong spring 785, and as controlled by the rotation of cam 780, is effective to rotate the ratchet wheel 793 a single step with each cycle of machine operation, whenever the follower member is released for operation. This feed of

ratchet gear 793 and shaft 760 occurs at approximately the midpoint of each cycle—in fact, within the first portion of the third quarter of each cycle. It can be noted at this point that when the auxiliary slide 730 of the operative order of the machine, has firmly abutted a shoulder 990 of cam 980, and is therefore unable to move forward, such blocking of the slide, through the idler 753 and feed gear 761, blocks rotation of the shaft 760, which, in turn, blocks the normal rocking of the follower member 781 from the force of its spring. This blocking of the operation of the follower member 781 will be utilized to control the carriage shift mechanism, through the medium of the shift control arm 327, as will presently be described.

It can be mentioned at this point, also, that in all operations of the machine, except in a multiplication operation with the multiplication control key 625 in its forward, or effective, position, the operation of the follower member 781 will be latched against operation. This can be secured by any suitable means. A preferred form is shown in FIG. 17, and comprises a rearwardly extending link 800, the forward end of which is pivotally mounted on the lower arm 787 of the follower member 781. The rear end of the link 800 is pivotally secured to a latching arm 801. The arm 801 is pivotally mounted on a transverse shaft 802 extending through the left frame plate 82. The upper end of the latching arm 801 carries a stud 803 which is engaged by the latching shoulder 804 of a latch member 805. The latch arm 805 is part of a bail, or gate, assembly including a second, and downwardly extending, arm 806, both of which are rigidly mounted on a common sleeve, or hub, 813 which rotates on shaft 807, whereby both levers rock in unison. A link 809 is pivotally mounted on the rear end of arm 805 by any suitable means, such as pivot stud 808. The lower end of the link is pivotally connected to a second latch arm 890, by any suitable means, such as stud 810. A spring 811, tensioned between the stud 810 and a stud, not shown, on the machine frame, biases the latch assembly, including the latch lever 805, into latching position (the position shown in FIG. 17).

The latch assembly just described is released by operation of the override pawl 190 (FIG. 5) previously described. A strong spring 820 (see FIG. 5) connects a stud 821 on the lower arm of the bellcrank 201 (which is rocked by the angular lever 196, upon operation of the override pawl 190) and a stud 822 on an arm 823 which is rigidly mounted on a shaft 824. Thus the rocking of the override pawl strongly biases the arm 823 and shaft 824 (counter-clockwise as viewed in FIG. 17). A slotted stop link 834 may be mounted on studs 821 and 822 in order to prevent over-rocking of shaft 824 beyond the position shown. The left end of the shaft 824 carries an arm 825 (FIG. 17) rigidly mounted thereon. A cam operating link 826 is pivotally mounted on the free end of the arm 825 and extends forwardly to a cam member 902, the construction and operation of which will be more fully described in connection with the description of the order selecting mechanism. At this point it can be noted, however, that the link 826 is provided with a stud 827 which abuts against the forward edge of the lower end of the arm 806. Thus the rocking of the override pawl rocks shaft 824 (counter-clockwise in FIG. 17), when the machine is conditioned for multiplication by the mechanism of the present invention, whereupon the stud 827 rocks the latch assembly, including the arms 806 and 805 (clockwise in this figure), to delatching position. It can also be noted that the link 826 carries a second stud 828 which may become engaged by the shoulder 829 of a latch arm 830. The latch arm is mounted on a stud 831 mounted on a bracket attached to the left frame plate 82, and is urged into latching position by a suitable spring 832. Thus the operation of the override pawl, acting through spring 820, resiliently biases the shaft 824 to an operative position (counter-clockwise direction in FIG.

17), which rocking, however, is blocked in ordinary operation of the machine by the inability of the cam 902 to shift its associated mechanism, as will hereafter be described. However, when the machine is conditioned for the present multiplication operation, the cam is free to operate, and consequently link 826, arm 825 and shaft 824 are free to rock upon operation of the override pawl. The translation of the link, as indicated, rocks the latch arms 806, 805 to release the multiplying feed mechanism; as heretofore indicated, and the link simultaneously is latched in the operative position by latch 830.

It can be noted in passing that the feed shaft 760 (FIG. 13) is also utilized in square root operations. However, it should be mentioned that the ratchet wheel 793 (FIG. 17), feed arm 781, and cam 780, are independent of the square root mechanism, and are in addition to feed mechanisms described in the square root patent. Separate feeding mechanisms for this shaft are necessary as feeds take place at different time phases of the cycle in the two operations.

6. Order selection mechanism

It has already been noted that normally the driving gear 761 (FIG. 13) of each order of the multiplier control mechanism, is disengaged from its driven idler 753. Means is provided for camming the driving gears 761 to the left, so that each can mesh with its associated idler, order-by-order beginning with the lowest order. In the preferred form of my invention, this mechanism is so constructed that one, and only one, order can be operative at any time. A preferred form of this camming means is shown in FIGS. 13 and 15, and comprises a cam 840 slidably mounted on a shaft 843 supported in the square root multiplier mechanism frame 751. The cam members 840 are provided with a flat surface, or base, 841 which abuts against the associated feed gear 761, and an opposed cone face 842 which is adapted to be engaged by a tooth 852 of an associated operating member 851. When a cam 840 is so engaged by its associated tooth 852, the cam will shift to the left on its shaft 843, thereby shifting the associated feed gear 761 into mesh with the associated idler 753. The cams are provided with spacing collars, or hubs, 844 which prevent over-shifting of the cams to the right, as shown in FIG. 15. It is preferred that the cams 840 be notched, as at 847 (FIG. 13), so as to enable the cam tooth 852 to quickly release the cam as the tooth starts to move away from its fully operative position, thus insuring that one cam will be released as the next one starts to move toward its operative position. When the cams are so notched, the cams should be held against rotation by any suitable means, such as a slot 845 in the cam member embracing a tie rod 846, as shown in FIG. 13.

The various ordinally arranged cams 840 are controlled by a single cam operating shaft 850. This shaft carries a number of single toothed cams, or operating members, 851, which are rigidly secured to the shaft in planes adjacent the slide cams 840. Each of these cam members is provided with a single tooth 852, which, when rocked to the proper angular position, will engage the conical face 842 of the associated slide cam 840, thereby moving the latter to the left. The teeth 852 on the cam members 851 are arranged in a spiral, or helix, with respect to each other, so that one, and only one, tooth can engage its associated cam 840 in any angular position of the shaft 850. Thus one, and only one, selection slide can be fed in any ordinal position of the carriage.

The cam operating shaft 850 extends laterally across the machine (longitudinal of the squaring mechanism frame 751) and is driven by a gear 853 (FIG. 15) which meshes with a similar gear 854 mounted on the square root cam shaft 855. I can use the cam feed utilized in the square root machine above-mentioned, as the cams are operated in the shifting cycle in both operations, and the fact that the two shafts operate in

opposite directions is handled by the feed gears 853, 854 just mentioned. Such a feed comprises a plurality of teeth 860 formed in the forward edge of the left end of the front carriage rail 124 (see FIG. 14). These teeth need only be formed to the left of, or outboard of, the selection mechanism. These teeth 860 engage the teeth of a gear 861 which is mounted on a stub shaft 862. The forward end of the stub shaft carries a worm gear 863 which engages a gear 864 mounted on the left end of the square root cam shaft 855. Thus the shaft 855 is rotated a single increment with each ordinal shift of the carriage.

Normally, the cam shaft 850 will lie in a right-hand position in which the teeth of cams 851 will be inoperative to operate the cams 840. The cam shaft is biased to this position by any suitable means, such as a compression spring 900 (see FIG. 12) embracing the left end of the cam shaft 850 and compressed between a cam collar 901 adjacent the left end of the shaft and the left-hand auxiliary plate 86, as shown. In a multiplication operation, the shaft 850 is shifted to the left by means of a cam 902 (see also FIG. 17) mounted on a suitable transverse shaft 903. Cam 902 has a laterally extending cam ear 905 which engages the collar 901, so that when the cam is rocked, the ear 905 pushes against collar 901 to shift the shaft 850 to the left. Cam 902 is pivotally connected to the forward end of the control link 826 by any suitable means, such as a stud 904. It can be mentioned that in all conventional operations, the shifting of shaft 850 is blocked by means of the blocking arm 720 shown in FIGS. 11 and 12. However, when this block is rocked away from the left end of the shaft 850, as it is by operation of key 625, then the operation of the override pawl will be free to rock shaft 824, translate link 826 and rock cam 902 to cam the shaft 850 to the left, against the force of its compression spring 900. When the shaft is so translated, the teeth of the cams 851 will be effective to shift the cam members 842 and thus cause the sequential engagement of the drive gears 761 with idlers 753. However, when the blocking arm 720 lies across the end of the shaft 850, the override pawl will be ineffective to translate the link 826, as the spring 820 will yield.

The blocking arm 720 is rocked from its blocking position shown in FIG. 11 (counter-clockwise in this figure) by the conjoint operation of the multiplying control key 625 and the depression of any of the multiplier keys 72, 73 or 74. It will be recalled that the blocking arm 720 carries a pin 722 (FIG. 11) which underlies the tail 637 of the slide 627 operated by the key 625. Thus, when the key is in its rearward, or inoperative, position, rocking of the lever 720 is blocked by the tail 637. It will be recalled, also, that the depression of any of the multiplier keys 72, 73 or 74, directly rocks the transverse shaft 371, and that an arm 594 (FIGS. 10 and 11) is mounted on the left end thereof. A link 911 extends from the upper end of the arm 594 to the lower arm of a two-armed rocker 912, being connected to the arm 594 by means of a pin, or stud, 910, and to the rocker 912 by means of a pin, or stud, 909. The upper arm of the lever 912 carries a pin 913 which is embraced within a slot 914 formed in the forward end of a link 915, the other end of the link being pivotally connected to the blocking arm 720. A spring 916 is tensioned between the pin 913 and a stud 917 on the link 915, so that the rocking of the lever 912 will resiliently bias the blocking arm 720 to an unblocking position (counter-clockwise in the position shown in FIG. 11). However, if the tail 637 blocks rocking of the blocking lever 720, then the spring 916 will yield upon rocking of the lever 912.

7. Shift control mechanism

Various means of controlling operation of the shift control arm 327 (FIGS. 9 and 17) could be suggested. However, I prefer the rather simple form shown in FIG.

17, which includes a second, or shift control, cam 870 mounted on the main drive shaft 107, adjacent the feed cam 780. Associated with the shift cam 870 is a two-armed follower 871 pivotally mounted on a transverse shaft 872. The forward arm of the follower lever 871 carries a roller 873 which engages the periphery of the cam 870. The follower roller is strongly biased into engagement with the periphery of the cam 870 by a relatively strong spring 874 tensioned between the lever and a stud, not shown, on the frame plate 82. The cam 870 is provided with a single, and rather sharp, depression 875 which begins about 200° from the full-cycle position and terminates at about the 270° position. Thus the follower lever will be biased into engagement with the periphery of the cam, and will be enabled to rock sharply (counter-clockwise in FIG. 17), beginning at about the 200° position, and some 20° or 30° behind the rocking of the feed follower 781. In the form illustrated herein, the sensing arm 871 is restored at about the 270° position while the feed arm 781 is not restored until shortly before the end of the cycle. However, the timing of restoration is not critical although the time of the operative stroke is critical—it is necessary that the feed arm reach the extreme of its stroke before the sensing arm becomes effective.

The rear end of the follower lever 871 overlies a pin 880 mounted on an arm 881. This arm 881 is rigidly mounted on an elongated hub, or sleeve, 886, rotatably mounted on the hub, or sleeve, 813 upon which is mounted arms 805 and 806. The other end of the sleeve 886 carries a bellcrank member 882, the forwardly extending arm 883 of the bellcrank 882 overlying the pin 510 on the shift control arm 327. Thus, whenever the follower lever 871 is rocked by the force of its spring, the consequent rocking of arms 881 and 883 will tend to depress the shift control arm 327 to initiate a shifting operation.

This shifting operation, resulting from the rocking of the bellcrank 882, is blocked in all conventional operations of the machine by means of a latch including the latch arm 890, controlled from arm 805. This latch arm is pivotally mounted on a short shaft 891, and carries a pin 892 which is adapted to engage the latching shoulder 893 formed in the rear arm of the bellcrank 882. The latch arm 890, as has previously been indicated, is connected to the link 809 by means of the pivot stud 810, and is, therefore, lifted to disengage the bellcrank 882 whenever the override pawl is operated in a register multiplying operation to shift link 826 and rock latch arm 805. It will be recalled that in a multiplying operation, the cam shaft shifting link 826 is free to move and therefore the bail, including the arms 806, 805 and the link 809, can be operated. However, when the multiplying control key 625 is in its inoperative position, movement of the cam shaft 850 is blocked, so that link 826 cannot be moved, latch arm 890 will remain in latching position, and bellcrank 882 remains inoperative.

The operation of the arm 883, from the strong bias of spring 874 of the shift cam follower 871, is also blocked whenever a feed of the feed shaft 760 is permitted. As shown in FIG. 17, the arm 883 carries a pin 884 slightly above, and to the rear of, the upper edge, or blocking face, 812 of the arm 801. The arm 801 is obviously rocked synchronously with the rocking of the feed follower 781, so that whenever a rocking of the feed follower is permitted, the arm 801 will be rocked rearwardly (counter-clockwise in FIG. 17), whereupon the blocking face 812 of that arm will underlie the pin 884. When this condition occurs, the arm 883 cannot rock, and the shift control arm 327 will not be operated. However, when rocking of the shaft 760 is prevented by the feed of the operative auxiliary slide being blocked by its engagement with a block, or stop shoulder, 990 of cam 980, as previously outlined, the operation of the feed follower 781 will be temporarily blocked, and (if the machine is conditioned for a register multiplying operation)

the shift follower 871 will be free to move under the bias of its spring 874 to follow the contour of the shift cam 870. In that event, arm 883 will be rocked, which will rock the shift control arm 327 and thereupon initiate a carriage shifting operation in the next machine cycle, as previously outlined. The entry of the value standing in the keyboard 60 will continue during the cycle in which the shift follower 871 and control arm 327 are rocked, but, of course, will not take place in the following shift cycle.

By the means thus described, the bellcrank 882 is operated by cam follower arm 871 and the force of its spring 874 whenever the control arm 801 is not operated to place the upper edge thereof under the pin 884 of the arm 883. That is, the bellcrank 882 is operated whenever a feed is blocked in the feed mechanism. The bellcrank 882 is latched in the rocked position until the following, or shift cycle of operation, for the follower arm 871 is immediately restored, but the shift control arm 327 must be held in its operative position until the shift cycle begins. This can be accomplished by means of a pin 885 on the rear end of the arm 882 engaging a shoulder 960 of a latch arm 961. This latch arm can be pivoted on any suitable point, such as the shaft 891 previously mentioned. The latch arm is biased into engagement with the pin 885 by any suitable means, such as spring 962. This latch is effective to temporarily hold the bellcrank 882 in its rocked position, thereby holding the shift control arm 327 depressed until the shift is initiated, although the follower arm 871 is immediately restored to its inoperative position by the cam 870.

Immediately after the shift is initiated, the latch 961 is released by mechanisms shown principally in FIG. 5. A plurality of ordinarily spaced rollers 963 are mounted on the rear side of the left end of the accumulator carriage 115 (to the right side of FIG. 5). Associated with the ordinarily spaced rollers 963 is a cam link 964 provided with a sharply pointed nose 965. In any ordinal position of the carriage, the nose 965 lies against the right side of the ordinarily related roller 963, so that the link will be operated at the start of any right shifting operation. The cam link 964 can be mounted for vertical movement in the machine by any suitable means, such as by being mounted upon the left end of a two-armed lever 966. The lever can be mounted on the rear of the machine by any suitable means, such as screw stud 967, and is biased by a suitable spring 968 into lifting the cam link 964 into engagement with the rollers 963. The lower end of the link 964, as shown in FIG. 17, is attached to the latching arm 961, as by stud 969. Thus, immediately after the start of a shifting operation, the latch 961 is released, whereupon the bellcrank 882 is restored to its normal position by the force of a suitable light spring 887.

When the bellcrank 882 is in its operative position, operation of the feed mechanism is blocked, not only by a blocking of an auxiliary slide, but also by the rear face of the arm 801 engaging the stud 884 on the arm 883. It will be recalled that immediately after a shift operation is initiated, the order selection mechanism is operated, so that the feed shaft 760 is unmeshed from the formerly operative auxiliary slide 730 and enmeshed with the auxiliary slide of the next higher order. This takes place early in the shifting cycle, thereby releasing the feed shaft 760 for operation. At approximately the same time the bellcrank 882 is released from its latch 961, and, as it is immediately returned to its inoperative position, a feed of the feed shaft can take place, which forces the auxiliary slide of the higher order a single step prior to the first digitation cycle in that order. The sequence of these operations is as follows:

(1) In the next to last cycle in an order the auxiliary slide engages stop face, or shoulder, 990 of the step cam 980 at the end of the feed operation, but this mere engagement has no effect on the control mechanism.

(2) In the last cycle of operation of the order, the cam 780 enables operation of the follower 781 at about the midpoint of the cycle (it starts at approximately the 165° position and is completed in about 45°), but the engagement of the auxiliary slide with the step cam 980 prevents further movement of the slide. This locks shaft 760 against further rotation and prevents rocking of the follower 781 and the latch arm 801. At approximately the 200° to 230° position, the arm 871 is operated, under control of cam 870, and, as the latch 801 is positively held out of blocking position, the follower 871 is enabled to rock shift control arm 327 to its effective position (in which position it is latched by arm 961). However, the operation of the shift control arm does not interfere with the completion of digitation in this cycle, for digitation begins early in the cycle, before the release of follower 781 by cam 780, and the conventional full-cycle mechanism (not shown) guarantees a completion of that operation.

(3) The operation of the shift control arm 327 in the third quarter of the last cycle of operation in the order centralizes the digitation control gate 116 and conditions the shift mechanism for a carriage shift operation in the next cycle. In the first part of the shift cycle, the latch 961 releases bell-crank 882 and at about the midpoint of this cycle the low part of cam 780 releases follower 781. At this point rotation of feed shaft 760 is unblocked for the disengagement of the cooperating cams 851 and 840, and the engagement of the corresponding cams of the adjacent higher order takes place early in the shift cycle. Thus the feed mechanism of follower 781, ratchet 793, shaft 760, gears 761, 753 and 750 and slide 730, takes place in the latter part of the shift cycle—at approximately the 270° position. It can be noted that the initiation of a carriage shift will immediately be effective to rotate the cam shafts 855 and 850 a single step, within the first few degrees of the cycle. As soon as these shafts are rotated, the previously operative cam 851 is rotated to release the previously operative cam 840, thereby enabling the spring 762 to force the previously operative drive gear 761 to the right, out of mesh with the idler 753, which unblocks the shaft 760. Simultaneously, the cam 851 in the next higher order of the machine will have engaged its associated cam 840, pushing it to the left and thereupon engaging the feed gear 761 of the next higher order with its idler 753. The release, or unlocking, of the shaft 760 occurs about the time the cam 780 reaches its 180° position, so that the force of spring 785 will sharply rock the feed follower 781 and effect a rotation of the shaft 760 for a single step. This delayed feed, during the ordinal shift of the carriage, is operative to shift the auxiliary slide of the next higher, or new, order a single step forwardly. It is conventional, at least in the machine referred to, to provide an interlock which prevents digitation and shifting in the same cycle. As the shifting operation was initiated first, the shift will continue throughout that cycle, and the digitation control shaft 118 and its related gate 116 will be held in their neutral position, so that the digitation control spool 110 will be completely disengaged from the accumulator gear 113. Thus the feeding of the auxiliary slide is not accompanied, during the shifting step, with any entry of the values into the accumulator, but it does shift the auxiliary slide the single step so as to block operation at the proper time. Conversely, in those cycles in which rocking of the feed shaft 760 is blocked, shortly after the initiation of the cycle, the mechanism is already in a digitation position, so that the machine will continue through that cycle, although the rocking of the shaft 760 later in the cycle, is blocked. By the means herein described, and the timing resulting therefrom, the digitation begun in the cycle in which the auxiliary slide firmly abuts against the depressed key, will continue, but the shift control arm 327 will be rocked in that cycle of operation to return the

digitation control gate 116 to its neutral position and to initiate a shifting of the carriage, as previously described. During the shifting cycle, no digitation will occur, but the auxiliary slide will be moved one position forwardly for the reason previously mentioned.

In the event the next higher order dial 75 stands at "0," the machine will continue the ordinal shift of the carriage without a digitation cycle in that order. It is obvious that the ear 731 on the auxiliary slide 730 normally will just abut the "0" shoulder 990 of the cam 980. When the digitation is completed in the next lower order, the controls just mentioned will cause a centralization of the digitation control gate 116 and a shifting of the carriage. During this shifting operation, the cams 780 and 870 operate as just described to prevent shifting of the digitation control gate to an operative position, although enabling a feed of the auxiliary slide 730 of that order forwardly at approximately a 180° to 270° position of the cams. This attempted feed of the feed slide 730 will, of course, be blocked by the "0" stop shoulder of the cam 980, so that the back pressure thereby created will prevent feeding or rotation of the shaft 760 and prevent operation of the follower lever 781. This holds the control arm 801 forwardly of pin 884 on the bellcrank 882. Thus, the shifting of the carriage will release the latch arm 961 but immediately the follower arm 871 will operate again to initiate a second shift.

8. Clearing mechanism

At the end of the multiplying operation it is desirable that the machine be restored to its normal position, and that all of the mechanisms herein described be returned to their normal positions, such as, for example, disengaging the cam link latch 830 (FIG. 17) to enable the return of the control shaft 824 to its original position. This matter can probably be most simply handled by mechanism operated from the override pawl on the left end of the carriage feed rack 179, and which is operated upon an attempt to shift the carriage beyond its extreme right-hand position. The override pawl 1000 (as shown in FIG. 5) is pivotally mounted on the left end of the rear of the carriage 51 by any suitable means, such as stud 1001, and is biased into its normal position shown by a suitable spring 1002. When the shift drive, including the drive plate 176, attempts to shift the carriage beyond the extreme right-hand position (toward the left in this figure), one of the pins 177 will engage the underside of the override pawl, rocking it (clockwise in this figure). The right end of the pawl is provided with a nose 1003, which, in that position of the carriage, overlies an ear 1004 on a lever 1005. In the conventional machine, the lever 1005 is a bellcrank, pivotally mounted at 1006 on a rear bracket 245 of the machine, and its rocking is effective to operate certain mechanisms not here pertinent. In my invention I extend the lever 1005 by adding a downwardly and leftwardly extending tail 1007, as shown in FIG. 5.

A link 1010 is supported by the free end of the extension 1007, and is connected at its lower end to an arm 1011 pinned on, or otherwise rigidly secured to, a short shaft 1012. The short shaft is journaled in a suitable bracket 1013 and in the left side frame plate 82 as shown. Thus the operation of the override pawl 1000 rocks the shaft 1012 (counter-clockwise in FIGS. 11 and 17). The rocking of this shaft serves several purposes: (a) it unlatches the ordinal shifting mechanism by releasing latch 961 (FIG. 17) which, in turn, releases the bellcrank 882, if it is latched in a shift initiating position; (b) releases the latch 830 and multiplying control link 826; (c) releases the depressed multiplier key and the mechanism controlled thereby; (d) it operates a keyboard clearing mechanism to clear the keyboard of the factor set therein, and (e) releases all the idler gears 753, thereby permitting the auxiliary slides 730 to return to their normal position.

(a) *Release shift latch 961.*—The latch arm 961 supports a depending link 1030 (shown in FIG. 17), the lower end of which is pinned to the forwardly extending arm of a two-armed lever 1031. This lever is pivotally mounted on a stud 1032 mounted on a bracket 1033 (see FIG. 11). As shown in FIG. 17, the rear end of the lever, or rocker, 1031 overlies a pin, or stud, 1034 in the forward end of an arm 1035, which is likewise rigidly mounted on the shaft 1012. Thus the rocking of the shaft 1012, from the operation of the override pawl 1000 (counterclockwise in FIG. 17), will release the latch 961 which is holding the bellcrank 882 in shift controlling position. It will be clear that when the carriage shifts into the extreme end position, the multiplying operation will continue in that order until the feed mechanism is blocked by the blocking of the auxiliary slide. Thereupon the shift control rocker 327 will be operated in the conventional manner and the control bellcrank 882 will be latched in the operative position. In this position of the carriage, however, the carriage cannot shift, so that the normal means for unlatching the bellcrank 882, including the cam link 964, cannot be operated. It is, therefore, necessary to provide means for unlatching the latch and releasing the shift mechanism from the operation of the override pawl itself.

(b) *Release the multiplying control link 826 and its latch 830.*—The rocking of the shaft 1012 preferably will be utilized, also, to release the latch 830 and the multiply control link 826, thereby returning the cam shaft 850 and latch arm 805 to their normal positions. In the preferred form of my invention I prefer to use the same operating linkage to clear the keyboard. It will be clear that the override pawl may be operated at other occasions, so that it is preferred that this clearing mechanism be yieldable and inoperative in some operations. This yieldable operation can best be secured, as shown in FIG. 11, by mounting an arm 1040 rigidly on the shaft 1012. Adjacent this arm is a second arm 1041, which is mounted for rotation on the same shaft. The free arm 1041 is biased toward the fixed arm 1040 by any suitable means, such as spring 1042 tensioned between studs 1038 and 1039 mounted on the respective arms. A stop pin 1037 prevents overrotation of free arm 1041 with respect to arm 1040.

The free end of the loosely mounted arm 1041 is provided with a pin 1043 which is embraced within a slot 1044 of a forwardly extending link 1045. The forward end of the link 1045 is pivotally supported, as by pin 1055, on an arm 1046 rockably mounted on the left control plate by any suitable means, such as screw stud 431. It can be mentioned at this point that the lifting of the link 1045 will be operative to release the multiplier control latch 830 (FIGS. 11 and 17). It can also be mentioned here that if the link 1045 is lifted by the rocking of arm 1041 and thereafter translated rearwardly, such translation will be effective to clear the keyboard, clear the multiplying mechanism by releasing the idlers 753 (FIG. 13) from their detents 770 and release the depressed multiplier key. In normal machine operations, however, the lifting of the rear end of link 1045 is prevented by a blocking member, or plate, 1047 on the link which underlies a pin 1048 mounted on an arm 1049. The arm 1049 is pivoted on the auxiliary, or control, plate 86 by any suitable means, such as screw stud 1050 and is biased into the blocking position by means of a spring 1051. The arm 1049 is moved out of blocking position by depression of any of the multiplier keys, which, it will be recalled, rock the shaft 371 and arm 594 (FIG. 11) to move link 911 and rock the two-armed lever 912. A link 1052 has its forward end pivotally mounted on the stud 909 which interconnects the link 911 with the lower arm of the lever 912. The rear end of the link is provided with a slot 1053 which embraces a pin 1054 carried by the arm 1049. Thus the rocking of shaft 371 (counterclockwise in FIG. 11) translates

the link 1052 rearwardly, moving the pin 1048 from above the block 1047. By the means just described, the lifting of the control link 1045 is blocked in all operations, except multiplication, from either the conventional mechanism shown in FIG. 6 or from the control of the present invention, by means of the block 1047 underlying the pin 1048. However, the arm 1049 and pin 1048 are moved to disengaging position by the link 1052, whenever any of the multiplier keys are depressed, so that in both types of multiplication operations the link 1045 is raised by the rocking of shaft 1012. The unblocking of the link 1045 in ordinary multiplying operations is unobjectionable, as conventional means would be used to terminate a multiplying operation, which would return the pin 1048 to blocking position, and if the multiplier unit were used to its utmost capacity, the operation would be terminated at this point in any event.

It will be recalled that the rocking of the override pawl 190, when the carriage reached its extreme left-hand position, caused the rocking of shaft 824 (FIG. 17), thereby moving the control link 826 rearwardly to set the various multiplying mechanisms to operative position. The link 826 was latched in this position by the latch 830. The forward end of the latch 830 is provided with a pin 1060 (see also FIG. 11), from which depends a link 1061. The lower end of the link is provided with a slot 1062 which embraces a pin 1063 on the link 1045. The slot 1062 enables the latch 830 to drop into latching position when a multiplying operation is initiated, but thereafter the lifting of the rear end of link 1045 will be effective to lift the link 1061 and thereby latch 830, releasing the multiplication control mechanism for return to its normal position from the force of the strong spring 820 (FIG. 5).

(c) *Multiplier key release.*—The link 1045 is provided with a bracket member 1070, which normally lies just below, and to the rear of, a pin 1072 mounted on an arm 1073. The arm 1073 is pivotally mounted on the frame plate by any suitable means, such as stud 1074, and is biased to the counter-clockwise position shown in FIG. 11 by a spring 1075. The arm 1073 preferably is rocked in each cycle of operation by means of a single toothed cam 1076, which may be the single tooth gear of the square root mechanism described in the square root patent above-mentioned. For this purpose the arm is provided with a rearwardly extending tail, or cam follower, 1077 which will be engaged by single tooth cam, or gear, 1076 at about one-third of the way through a cycle of operation. When the rear end of the link 1045 is lifted by operation of the override pawl, the ear 1071 of bracket 1070 will lie immediately behind the pin 1072, so that the rocking of the arm 1073 (clockwise in FIG. 11) immediately thereafter will translate the link 1045 rearwardly.

The translation of the link 1045, by the means just described, will be effective, among other things, to release the depressed multiplier key. For this purpose I prefer to provide a short link 1080 pivotally mounted on, and extending forwardly from, the arm 1046 which supports the forward end of the link 1045. The forward end of this link 1080 is provided with a slot 1081 which embraces a screw stud 1082 in the lower end of a lever 1083 rigidly mounted on the latch shaft 363. Thus the arm 1083 and shaft 363 are rocked (clockwise in FIG. 11) by the rearward translation of the link 1045. It will be recalled that the shaft 363 carries the latches 365 (FIG. 9) and 360 (FIG. 7), so rocking of the shaft 363 releases any of the depressed multiplier keys. Release of the multiplier key, of course, terminates the multiplication operation. It also permits the shaft 371 to return to its normal position, thereby restoring the blocking pin 1048 to its blocking position, and rocking the cam shaft blocking plate 720 (FIG. 12) to its blocking position, and otherwise normalizing the control mechanism of the machine.

(d) *Clearing keyboard.*—It is also desirable to clear

the keyboard of the machine at this stage of operation, in order that the machine will be ready to receive another problem. Incidentally, this operation in the square root machine above-mentioned, will release the detents 770 (FIG. 13) to permit the idler gears 753 and auxiliary slides 730 of the feed mechanism to return to their neutral, or inoperative, position. This clearing can be secured by means of a link 1090 (FIG. 11), the rear end of which is provided with a slot 1091 that embraces the pin 1055 which joins the link 1045 to the arm 1046. Thus, the rearward translation of the link 1045 will also cause translation of the link 1090, although permitting that link to be operated in other operations. The forward end of the link 1090 is supported by a depending arm 1092 which is rigidly mounted on a shaft 1093. The shaft 1093 extends across the front of the machine, and its right end is shown in FIG. 18. Adjacent the right side supporting plate 81, the shaft 1093 carries an arm 1094 which is adapted to engage a clearing bail 1095. The clearing bail is mounted between the frame plates 81 and 82 by any suitable means, such as on shaft 1096, as is conventional in machines of this character. It is conventional in the machine mentioned, to provide the ordinal latch slides 92 (see also FIG. 2) with depending ears 1098, which are adapted to be engaged by the rearwardly extending flange 1097 of the clearing bail 1095. It is evident that the rocking of the bail 1095 will be effective to move all of the locking slides 92 rearwardly, thereby releasing any of the keys of the keyboard which have been locked in a depressed position. Thus the rocking of the shaft 1093, caused by operation of the override pawl 1000, will be effective to operate the clearing bail 1095 and, among other things, clear the keyboard of the machine.

(e) *Normalize the auxiliary slides.*—It is more important that the rocking of the shaft 1093 be utilized to clear the idler gears 753 (FIG. 13), in order to return the auxiliary slides 730 to their normal position. I prefer to utilize for this purpose, the clearing mechanism shown in the square root machine, Patent No. 2,736,494 above-mentioned. As shown in that machine, this is accomplished by means of a lever 1100 (FIG. 18) pivotally mounted on the right frame plate 81 by any suitable means, such as shaft 1101, which lever is operated by rocking of the clearing bail 1095. The lever 1100 supports the forward end of a rearwardly extending link 1102, the rear end of which is provided with a slot 1103 which embraces a shaft 1104. The link is biased to its retracted, or inoperative, position by means of a suitable spring 1107, as shown.

A bracket 1105 on the rear end of the link 1102 carries a roller 1106, as shown in FIGS. 18 and 19. The roller 1106 abuts against the angled end, or cam projection, 1110 of the transverse slide 1111. This slide is provided with guide slots 1112 which embrace guide pins 1113, thereby providing for transverse movement of the slide. Normally this slide is biased toward the left by a resilient means, such as a spring, not shown. The upper edge of the slide 1111 is provided with a plurality of notches 1114 within which lie the tails 774 of the detent members 770. One edge of the notches 1114 is slanted to form a cam face 1115, so that the translation of the slide 1111 (to the left in FIG. 19) from the translation of the slide 1102, causes the cam faces 1115 to lift the tails 774 (counter-clockwise in FIG. 13) of the detent members, thereby releasing the idler gears 753 and the auxiliary slides 730. In this manner, the auxiliary slides are enabled to return to their normal, inoperative, position from the bias of their respective springs 734, and the multiplying mechanism is returned to its normal condition.

9. Operation

It is believed that the operation of the multiplying mechanism of the present invention is obvious from the

preceding description. However, it can be summarized very briefly. The multiplier value is set into the multiplier register dials 75, either directly from the keyboard keys 60 or by an interregister transfer from the inboard accumulator dials 52, and the multiplicand value is set into the keyboard keys 60. The setting of the value in the keyboard keys 60, of course, locks the operated keys in their depressed position by operation of the ordinal locking slides 92. The multiplier control key 625 is moved to its forward, or operative, position—which can be done either before or after setting of the values in the keyboard and multiplier register dials 75. Thereafter, one of the multiplier keys 72, 73 or 74 is depressed, depending upon the program of operation desired. In any event, the depression of any one of these keys results in the rocking of the shaft 371 (FIGS. 7 or 10), which initiates a continuous left shift of the carriage and simultaneously tends to condition the power clearing mechanism for operation when the carriage reaches the extreme left-hand position. It will be understood, of course, that if either key 73 or 74 has been depressed, the rocking of arm 590 (FIG. 10), through link 597 and arm 598, rocks shaft 599 to disable the register clearing clutch and the mechanism controlled thereby. When the carriage reaches the extreme left-hand position, the override pawl 190 (FIG. 5) is operative, through bellcrank 201 and link 202 (FIGS. 4 and 5), to rock the bail 204, and thereby disable the left shift clutch and the clear clutch and simultaneously to enable the multiplier mechanism by means of link 412 (FIG. 7), arm 415, shaft 416, and latch 417 (FIG. 10). The operation of the override pawl 190, through operation of bellcrank 201, the force of spring 820 (FIG. 5), arm 823, shaft 824, and arm 825 (FIG. 17) also operates the link 826 to rock cam 902 to its operative position and thus displace the cam shaft 850 to the left so as to effect operation of the ordinal setting cams 840 (FIG. 13) in sequence—the joint operation of the key 625 and the rocking of shaft 371 having moved blocking arm 720 to its unblocking position. The shifting of the carriage to the extreme left-hand position has placed the cam tooth 852 of the lowest order of the machine, in operative position, so that the translation of the shaft to the left causes the engagement of the drive gear 761 of the lowest order with the idler 753 of that order to cause the step-by-step feed of the lowest order auxiliary slide 730. The slide is fed one step during the override cycle, during which time the digitation control gate 116 remains in its neutral position. At the end of this cycle, the gate 116 is set for registration and the value set in the keyboard is registered in the accumulator with each cycle of machine operation. Simultaneously therewith the auxiliary slide 730 is fed forwardly until, in the next to the last cycle of operation in that order, the ear 731 on the auxiliary slide just engages the proper value shoulder 990 on the cam 980. Then in the next (last ordinal) cycle, the forward movement of the auxiliary slide 730 is blocked by the engagement with the associated stop shoulder on the cam, which action takes place after the digitation phase of the cycle has started, and, therefore, too late to centralize the digitation control gate in that cycle and the conventional interlock prevents neutralizing of the digitating control gate 116 until the end of the cycle. However, in that cycle, the back pressure on the auxiliary slide, operating through idler 753, feed gear 761 and shaft 760 (FIG. 13), prevents operation of the feed pawl 790 (FIG. 17), thereby holding the follower lever 781, link 800, and control lever 801 in the full-cycle position shown. The holding of the control arm 801 in the full-cycle position enables the operation of the bellcrank 882, under the control of cam 870, from the force of spring 874. The operation of bellcrank 882 rocks the shift control lever 327 to centralize the digitation control shaft at the end of that cycle of operation and to initiate a shift in the next cycle. Later in the shift cycle, the shifting control linkage is released, which causes the disengagement of the feed gear 761

(FIG. 13) of the previously operative order from its idler 753, and the engagement of the adjacent drive gear 761 with the idler in the next higher order—which permits the incremental feed of shaft 760 to occur, although somewhat later than ordinary, in that cycle. This enables a feed of the slide 730 of the next higher order, one step forwardly, although the centralizing gate is still in its neutral position so that digitation does not occur until the second cycle after the operation of the shift control lever. This sequence of operation continues until the machine reaches its extreme right-hand position, whereupon the override pawl 1000, at the end of the shift rack, is operated to release the mechanism and return all the parts to their original full-cycle position. At this time the machine is cleared for a subsequent operation.

III. SQUARING MECHANISM

A second embodiment of the present invention, and one which has considerable value in combination with a square root machine of my joint patent above-mentioned, is one directed to a squaring operation as distinguished from ordinary multiplication. This second embodiment is directed primarily to a machine of the type disclosed in the Friden patents above-mentioned, and more specifically to the square root machine of my joint patent. The machine of this embodiment would not be equipped with the multiplier storage dials 75, or means for transmitting values from the keyboard or the accumulator register into a multiplier storage cam. In other words, this embodiment is particularly adapted to square a value standing on the keyboard, using the square root mechanism for that purpose, and can be included in either a conventional "Friden" calculator of the type disclosed in the Friden patents or the square root machine of my previous invention. It will be understood, however, by those skilled in the art, that the mechanism of this embodiment, as in the preceding one, can be used in any conventional calculating machine using differentially set selection slides or members.

As in the first embodiment, I prefer to use the machine above-described, for it is most convenient to utilize the various multiplication control keys, such as multiplication key 72, accumulate multiplication key 73 and negative multiplication key 74, to initiate similar types of squaring operations. These keys will set the digitation control gate as described in connection with the conventional multiplication mechanism, and operate the shifting and clearing mechanisms in the same programs as in multiplication. Means will be provided, identical with those of the first embodiment, to disable the rocking of the control shaft 324, so that the feed of the multiplier control segments will be disabled throughout the operation; and disable the multiplier carriage shift mechanism including the shift control arm 339 and the feed pawl 335, as by lifting the feed pawl and its hub 336 above the path of operation of pin 340 on arm 339. In this form, as in the preceding one, I will utilize the rocking of the shift control lever 327, 502 to terminate an operation in one order of the machine, to temporarily centralize the digitation control shaft 118, to cause a shifting of the register carriage a single step toward the right, and to reinitiate a multiplication operation in the new order.

Needless to say, the squaring operation, in the present embodiment, is controlled by values set in the main keyboard 60 rather than in the multiplier keyboard 70 or register dials 75, whereby the value set in the main keyboard 60 is multiplied by itself. In order to accomplish this purpose, I provide auxiliary slides associated with each order of the machine, similar in purpose to slides 730 of the first embodiment but slightly different in form, which slides are fed forwardly a single step with each cycle of machine operation until forward movement is blocked by the auxiliary slide, by means of an interponent engaging a depressed key in that order. The engagement of the interponent with the depressed key, by blocking movement of the auxiliary slide, results in rocking the

shift control arm 327 to thereby initiate the conventional program, including centralizing the digitation control shaft 118 and initiating a single shift of the carriage to the right. While the form of the auxiliary slide is slightly different, the method for feeding it forwardly step-by-step with each cycle of machine operation, and the means for selecting the order in which the slide is to be fed, is identical with that utilized in the first embodiment, and, therefore, similar to that of my square root patent. As a matter of fact, in its preferred form, my present invention can be associated with the mechanism of that joint patent so that a single machine will be capable of extracting square root and of squaring factors, for the most part, utilizing the same feed mechanisms.

15 Generally speaking, the mechanism of the present embodiment is the same as that of the first embodiment, described in Part II, entitled "Storage Register Multiplying Mechanism." Specifically, the method of operation is essentially the same as that previously described, except 20 that in this embodiment, the multiplier cams 980 described in Section 4 of the first embodiment and the multiplier dials 75 are completely eliminated. In the present form, or embodiment, the auxiliary slides are modified, as will hereinafter be described, and a "0" blocking mechanism 25 should be provided. With these specific exceptions, the mechanism of the present embodiment will be the same as that above mentioned.

1. Method of operation

30 From what has been said, it is believed obvious that the squaring operation of the present invention is accomplished by use of the auxiliary slides of the square root mechanism, one of which slides is associated with each order of the keyboard. These slides are operated one at 35 a time and are fed forwardly in single increments, or steps, with each cycle of machine operation. In the present embodiment, such operation is continued until movement is blocked by engagement of an interponent associated with each such slide with a depressed key in that 40 order.

The inventive concept in this embodiment lies in providing an interponent means between the feed, or square root, slide and the ordinally related selection slides, so that operation of the slide will be blocked when the slide 45 has been moved forwardly a number of steps corresponding to the value in that order of the keyboard. As in the preceding embodiment, it is desirable that the slide be fed forwardly, in the lowest order, in the cycle in which the override pawl is operated, and in all other orders with 50 each shift cycle, so that the interponent will just engage the depressed key stem in the digitation cycle corresponding to one less than the keyboard value of that order; and in the succeeding cycle, the interponent and slide will be blocked although digitation will continue. As 55 in the preceding embodiment, the progressive movement of the slide continues until further progress is blocked by the engagement of the interponent with a depressed value key in that order, whereupon the back pressure on the slide causes the disengagement of the digitation control 60 gate 116 and the digitation gears at the end of that cycle, initiates a carriage shifting operation which simultaneously changes the order in which the slide feed will be operative, and reinitiates operation in the higher order.

The auxiliary slides herein mentioned are substantially the same as the auxiliary slides utilized in the square root patent, with one exception which will be noted herein under the heading of "Auxiliary Slides."

2. Conditioning key

70 The construction of the conditioning key 625 for this embodiment is identical with that described in the first form, and, therefore, need not be described again. It will be understood that the operation of this key will be effective to: (a) retract the tip of the shift control arm; (b) disable the multiplier keyboard; (c) disable the mul-

tiplier feed pawl; (d) disable the multiplier carriage shift pawl; (e) condition the machine for right shift from any operation of the shift control arm, regardless of the multiplier carriage position; and (f) condition the squaring feed mechanism of the present form of this invention under control of the conventional multiplication keys 72, 73 or 74, all as described in connection with the previous embodiment.

3. Auxiliary slides

In the second, or squaring, form of my invention, I provide an auxiliary slide 730-a associated with the selection bars 96 of each order of the machine. In the form shown in the drawings (FIGS. 20 to 22, inclusive) the auxiliary slides 730-a are slidably mounted in slots, not shown, in the crossbar member 83 (see also FIG. 2) and the comb 732 at the forward part of the selection mechanism (FIGS. 20 and 21). These slides are resiliently biased toward the rear, to an inoperative position, by any suitable means, such as a spring 734-a tensioned between a spring seat on the comb 732 and a nose 733-a projecting from the forward end of the slide. Each of these slides is provided with a projecting ear, or bracket, 731-a passing laterally through notches 736 formed in the lower edges of the ordinally related selection slides. It will be recalled that in the machine shown in the drawings, there are two selection bars 96 for each order of the machine, one serving the "1" to "5" keys and the other the "6" to "9" keys. In such a machine the forward movement of the auxiliary slide 730-a will first move the "1" to "5" selection bar forwardly through its five differential positions before engaging the "6" to "9" bar, after which the "1" to "5" bar will remain stationary while the "6" to "9" bar moves. This is best accomplished by means of a slide 737 (see FIG. 22) mounted on the right side of the "1" to "5" selection slide by pin-and-slot mountings 738 and urged to the rear by a suitable spring 739 tensioned between a stud, not shown, on the selection bar and a stud 741 on the yieldable interponent 737. The interponent is provided with a downwardly projecting nose 742 which is engaged by the bracket 731-a of the auxiliary slide, whereby movement of the auxiliary slide 730-a directly moves the interponent 737. Movement of the interponent, by the force of the spring 739, translates the "1" to "5" selection bar forwardly until forward motion of the selection bar is blocked as by abutting against the front crossframe 87, for it cannot exceed forward movement equivalent to five differential positions, or values, after which the spring yields.

It will be recalled that it has been mentioned that the mechanism of the present invention is designed particularly for use with the machine for the extraction of square root described in my joint patent above-mentioned. It can be mentioned that in the extraction of square root, the auxiliary slide 730-a is moved forwardly by the machine step-by-step with each cycle of machine operation, and that this forward movement is utilized to place the selection bars in the proper differential position for the extraction of square root. It is desirable to provide an auxiliary slide 730-a that will serve both for the extraction of square root and for the squaring operation. In this invention the selection bars are moved forwardly differential amounts, depending upon the value of keys depressed, and the auxiliary slides 730-a will be moved forwardly step-by-step with each cycle of machine operation until the bracket 731-a abuts against the blocked, selection slide, and when forward motion is so blocked it operates the yieldable connection to terminate operation in that order of the machine and cause a shift of the carriage to initiate repetitive operation in the next higher order. For this reason the interponent 737 is modified from that shown in the square root machine by providing thereon noses 743 (FIG. 22), which, in the normal position of the interponent 737 with respect to the

selection bar, lie adjacent the notches 103 provided at the bottom of the cam faces 101 on the "1" to "5" selection bar. Thus the depression of a value key "1" to "5" will cause a similar forward movement of the interponent 737, which causes the key pin 102 to abut against the forward face of the associated nose 743, thereby blocking the interponent 737 against forward motion beyond this position. It is necessary to provide such notches in the interponents 737, for without them the spring 739 (which is necessary to enable operation of the "6" to "9" selection bar) would permit the interponent to move forwardly beyond the value position of the "1" to "5" selection bar; thereby enabling a false operation, for it is the back-pressure on the auxiliary slide 730-a caused by either the interponent or the "6" to "9" bar, which terminates the squaring operation in that order. It will be obvious that no such interponent is necessary on the "6" to "9" bar as there is no yieldable connection between the auxiliary slide 730-a and that selection bar.

The auxiliary slide in the operative order is given a single step of forward movement with each cycle of machine operation by means of the rack 735 formed on the rear end of the slide, which rack meshes with a drive gear 750 which is given the necessary step operation, as was previously described in Part II, sections 5 to 7, inclusive.

4. Multiplier control

In this embodiment no multiplier cam 980 is necessary, and, in fact, there is no need for a shaft corresponding to shaft 981 in the square root machine of my joint patent above-mentioned, so that the elements described under this heading in the first embodiment are completely eliminated.

5. Slide feeding mechanism

This mechanism is identical with that described in the first embodiment.

6. Order selection mechanism

This mechanism is identical with that described in the first embodiment.

7. Shift control mechanism

This mechanism is the same as that described in the first embodiment.

8. Clearing mechanism

This mechanism is exactly the same as described in the first embodiment.

9. Zero block

The rocking of the shaft 824 (FIGS. 5 and 17) to set multiplication control link 826 and cam 905, from the operation of the override pawl 190, as previously outlined, is preferably effective to block operation of the auxiliary slides in all orders in which the values stand at "0." The mechanism for this purpose is shown primarily in FIGS. 24, 25 and 26. Various forms of mechanism could be suggested, but I prefer to utilize the mechanism shown, which comprises a series of ordinally arranged slides 920 mounted on a forward crossframe member 921 which is affixed to bar 732. The slides are mounted for vertical movement by means of a suitable pin-and-slot connection, including pins 922 mounted on the crossbar embraced by a slot 923 in the slides. The slides 920 are mounted immediately in front of the respective selection slides 96 and their interponent slides 737. When any slide 920 is in a depressed position, the ordinally related selection and interponent slides are free to move, but when the slides 920 are in their raised position, the upper portion thereof lies immediately in front of the selection and interponent slides and effectively blocks movement thereof. Also, the slides 920 are free to move upwardly when both selection slides and the interponent slide of the respective orders are in their "0" positions,

but are individually blocked against such movement if either of the selection slides or the auxiliary slide are moved forwardly a single unit space. These slides are individually biased to a raised position by springs 924 tensioned between the upper pin 922 and a pin 925 in the lower end of the slide. The pins 925 underlie a bar 926, which is rockably mounted in the frame by any suitable means, such as arms 927, and is held in its depressed position by means of a suitable bellcrank 928 which is biased to the depressed position by a strong spring 929. This spring is stronger than the combined springs 924, so that it overcomes the force of these springs and normally holds the bar and the slides in a depressed position. Thus, normally, the ordinarily arranged "0" blocking slides 920 are held in a depressed position by means of the bar, or bail, 926 acting under the force of spring 929, and the selection slides 96 and auxiliary slides 730 normally are free to move.

The bail 926 can be lifted to an operative position by operation of the override pawl 190, which, by the mechanism shown in FIG. 5 and previously described, rocks the shaft 824 in squaring operations. It will be recalled that this shaft is latched in its operative position throughout the squaring operation, by means of the latch arm 830 (FIG. 17) which engages the pin 828 on link 826. Referring now to FIGS. 24, 25 and 26, it is seen that a two-armed lever 940 is pivotally mounted on the base plate by any suitable means, such as screw stud 941. The left-hand arm of this lever carries a cam bracket 942, which, when the lever is rocked (counterclockwise in FIG. 24) cams the bail 926 upwardly. Normally, the lever 940 is held in its inoperative position by the force of spring 943 tensioned between an ear 939 on the lever and a suitable seat, or stud, on the frame plate, not shown. The opposite end of the lever 940 is provided with an ear 944, through which is inserted a rearwardly extending tie rod 945. The rear end of the tie rod 945 is shown in FIG. 5, and is threaded through an ear of a bellcrank 946. The bellcrank 946 is pivotally mounted on a bracket 947 mounted on the base plate. A horizontal arm of the bellcrank 946 is pivotally connected to an upwardly extending link 948, the upper end of which is mounted on the forward end of an arm 949 pinned to, or otherwise rigidly mounted on, the shaft 824.

It will be recalled that the shaft 824 is rocked counterclockwise when viewed from the left, as in FIG. 17, thereby lifting the arm 949 and link 948, rocking bellcrank 946 and pulling the tie rod 945 rearwardly. The rearward translation of the tie rod 945 rocks the lever 940 (counter-clockwise in FIG. 24), causing the cam 942 thereon to lift the gate, or bail, 926. This permits the slides 920 to rise individually, unless blocked by the selection slides 96 or the auxiliary, or feed, slide 730-a of the associated order. It will be seen in FIG. 24, that normally the forward end of the selection slides 96 and the auxiliary, or feed, slide 730-a, register with the forward wall of the cross plate 921. If one of these slides has registered a value, even a single increment of motion, such as a value of "1" or "6," the forward end of one of the selection slides 96 will overlie the upper edge of the ordinarily related "0" blocking slide 920, thereby preventing operation of the latter. Thus the "0" blocking slide 920 will be inoperative in all orders in which a value has been set. On the other hand, if no value stands in the selection slides of a particular order, then the ordinarily related "0" slide 920 clears the forward end of the selection slide and the "0" blocking slide 920 is free to rise. In that event the operation of the override pawl frees the various "0" blocking slides 920 for operation by their individual springs 924, enabling them to rise in front of the selection slides of all orders in which a "0" is registered. In that event, a forward feed of the selection slides is impossible, thereby preventing any digitation operation in that order. It will be recalled that in each ordinal shift of the carriage, after the initiation

of the shift, the squaring feed mechanism is operated to feed the auxiliary slide 730-a and the ordinarily related selection slide a single step. If, in this cycle of operation, the selection slides abut against the "0" blocking slides, then another shift is initiated and the carriage is shifted to the next higher order without a value being registered in that order.

10. Operation

It is believed that the operation of the second embodiment of the machine of my invention will be obvious from the preceding description. However, it can be summarized very briefly. The value to be squared is set into the main keyboard which comprises the value keys 60. The setting of the values in the keyboard 60, of course, locks the operated keys in their depressed position, by operation of the locking slide 92. The squaring key 625 is moved to its forward, or operative, position—either before or after the setting of the value in the keyboard. Thereafter one of the multiply keys 72, 73 or 74 is depressed, depending upon the program of operations desired. In any event, the depression of one of these keys results in rocking the shaft 371 (FIG. 7 or 10), which initiates a continuous left shift of the carriage, and, if the key 72 has been depressed, also enables the operation of the clearing mechanism when the carriage reaches the extreme left-hand position. When the carriage has reached the extreme position, the override pawl 190 is effective, through the tie rod 945 (FIG. 24), to operate the "0" blocking slides 920 and thus lock all of the selection slides against operation if no value had been inserted in their order. The operation of the override pawl 190 also operates the link 826 (FIG. 17) to rock cam 902 to its operative position, and thus displace the cam shaft 850 to the left so as to be operative upon the ordinal setting cams 840 in sequence. The shifting of the carriage has placed the cam tooth 852 of the lowest order of the machine in operative position, so that the translation of the shaft to the left causes the engagement of the idler 753 of that order with the drive gear 761 to cause feed of the auxiliary slide 730-a in that order. The slide is fed one step during the override cycle, during which time the digitation control gate 116 remains in its neutral position. Thereafter the gate is set for registration and the value set in the keyboard is registered in the accumulator with each cycle of registration. Simultaneously therewith, the auxiliary slide 730-a is fed forwardly until further movement is blocked by the auxiliary slide engaging a latched interponent 737 associated with the selection slide 96. The back pressure on the auxiliary slide, operating through the idler 753, drive gear 761 and shaft 760, prevents operation of the feed pawl 790 and thus enables operation of the bellcrank assembly 882 by the follower arm 871, the operation of which is timed by the cam 870. When such operation occurs, the bellcrank 882 causes operation of the shift control arm 327, thus centralizing the gate 116 in the next cycle of operation and causing a shift of the carriage to the right. Later in that shift cycle the shifting control linkage is released, which permits the feed of shaft 760 to occur, although somewhat delayed in the cycle. This feeds the auxiliary slide in the next higher order one step forwardly, although the centralizing gate is still in its neutral position, so digitation does not occur until the second cycle after operation of the shift control lever. This sequence of operations continues until the machine reaches its extreme right-hand position, whereupon the override pawl at the end of the shift rack is operated to release the mechanism and return all the parts to their original full-cycle position. At this time the machine is cleared and ready for a subsequent operation.

It will be understood that the drawings shown herein, and the description of the construction and operation of the mechanism of my invention are illustrative of a

preferred embodiment of the invention, but that the invention is not to be limited strictly to the apparatus so shown and described. The principles here described could be utilized with other commercial calculating machines, other than the one shown, and many changes could be made in the construction arrangements of the parts without departing from the spirit of the invention.

I claim:

1. In a calculating machine having an ordinarily arranged and cyclically operable digitating means, a register shiftable with respect to said digitating means, and means for shifting said register, the combination which comprises multiplier value registering members associated with selected orders of said digitating means, means for positioning said members to represent selected values, a movable member associated with each one of said selected orders of said digitating means, means for translating a selected one of said movable members a predetermined amount with each cycle of machine operation, such motion being in a direction to engage the positioned value registering member of the selected order, means for sequentially selecting the movable member to be so translated, and means operated upon the engagement of the movable member with its associated value registering member for controlling operation of said shifting means, said sequential selecting means, and said digitating means.

2. In a calculating machine having a value indexing means including an ordinarily arranged selection means, a register shiftable with respect to said selection means, a cyclically operable computing means for entering a value determined by said selection means into said register, and means for shifting said register, the combination which comprises positionable members for registering a multiplier value associated with selected orders of said selection means, means for positioning said positionable members to represent selected values, a plurality of ordinarily arranged movable members each associated with said selected orders of said selection means, means for moving a selected one of said movable members a predetermined amount with each cycle of operation of said computing means in a direction to engage the positioned value member of the ordinarily associated order, means for selecting sequentially the movable member to be moved, and means operated upon the engagement of the movable member with its coordinal value member for operating the shifting means and disabling the computing means.

3. In a cyclically operable calculating machine having an ordinarily arranged digitating means, a selection mechanism for controlling operation of said digitating means, a register shiftable with respect to said digitating means and means for shifting said register, the combination which comprises a positionable value member associated with selected orders of said digitating means, means for positioning said value members to represent a value, a plurality of ordinarily arranged movable sensing members associated with the said selected orders of said digitating means, means for moving said sensing members a predetermined amount with each cycle of machine operation in a direction to engage the coordinal value member, means operated upon the engagement of the sensing member with the coordinal value member for operating the shifting means, and means for connecting said sensing members to said moving means in a predetermined ordinal sequence.

4. In a cyclically operable calculating machine having an ordinarily arranged selection mechanism, ordinarily arranged digitating means controlled by said selection mechanism, a register shiftable with respect to said digitating means, means for shifting said register, and a cyclically operable drive means, the combination which comprises a plurality of ordinarily arranged positionable value members associated with selected orders of said digitating means, means for positioning said value members, a movable sensing member associated with the said

selected orders of said digitating means, means operated by said drive means for differentially moving said sensing members in a direction to engage the coordinal value member, ordinal interponents for operatively connecting said sensing members to said moving means, means operated upon the engagement of a sensing member with the coordinal value member for operating the shifting means, and means operated by said shifting means for sequentially selecting one only of said interponents for operation to connect its respective member to said moving means.

5. In a calculator having an ordinarily arranged selection mechanism, a register shiftable with respect to said selection mechanism, means for shifting said register, and a cyclically operable digitation means operable to differentially operate said register in accordance with values set in the selection mechanism, the combination which comprises a plurality of ordinarily arranged value cams associated with selected orders of said selection mechanism, means for positioning said cams to represent a selected value, a member associated with each order of the cams and movable to positions determined by the position of the cam in that order, means for feeding a selected one of said members a predetermined increment with each cycle of operation of said digitation means, and means operated upon the engagement of the selected one of said members with its coordinal cam for terminating operation of said digitating means and initiating a cycle of operation of said shifting means.

6. In a cyclically operable calculator having an ordinarily arranged keyboard, a register shiftable with respect to said keyboard, means for shifting said register, and a cyclically operable digitation means to differentially operate said register in accordance with values set in the keyboard, the combination which comprises a plurality of ordinarily arranged value cam members each settable to represent a multiplier value, a plurality of movable control members each respectively associated with one of said cam members and movable into engagement with the ordinarily related cam member, feed means for moving said control members a predetermined increment with each cycle of operation of said digitation means, means for sequentially connecting said control members to said feed means, means operated upon the engagement of a moving control member with the ordinarily related cam member for terminating operation of said digitating means and initiating a cycle of operation of said shifting means, and means operated by said shifting means for operating said connecting means to disconnect the previously connected control member and to connect another control member to said feed means.

7. In a cyclically operable calculator having an ordinarily arranged keyboard, a register shiftable with respect to said keyboard, means for shifting said register, and a cyclically operable digitation means to differentially operate said register in accordance with values set in the keyboard, the combination which comprises multiplier value registering members associated with selected orders of said keyboard, means for setting said multiplier members to represent selected values, control members each respectively associated with one of said multiplier members and movable into engagement with the ordinarily related multiplier member, feed means for moving said control members a predetermined increment with each cycle of operation of said digitation means, means for sequentially connecting said control members to said feed means, means operated upon the engagement of any of said control members with the ordinarily related multiplier member for terminating operation of said digitating means and initiating a cycle of operation of said shifting means, and means for blocking operation of said control members in all orders in which no multiplier member has been operated.

8. In a calculator having an ordinarily arranged differentially positionable selection means including a plurality of ordinarily arranged value indexing members, means

for setting said indexing members to represent various digital values, an ordinarily arranged accumulator, a cyclically operable digitation means for entering a value determined by said selection means into the accumulator, and means for shifting said accumulator with respect to said selection means, the combination which comprises a plurality of ordinarily arranged value sensing means movable to sense the value set in the ordinarily related indexing members, power driven feed means for moving said value sensing means predetermined increments of motion with each cycle of operation of said digitation means, a plurality of ordinarily arranged interponents positionable to connect said drive means to the ordinarily associated value sensing means, means for positioning one only of said interponents in operative position at a time, and means operated by the sensing means upon sensing an index member for operating said shifting means and thereafter operating said positioning means to move the previously operable interponent into inoperative position and position another interponent in operative position.

9. The apparatus of claim 8 wherein the sensing means comprises ordinarily arranged slides, one associated with each order of the selection means, and the predetermined increments of motion of the sensing means correspond to the differential positions of the differentially positionable selection means.

10. The apparatus of claim 8 wherein the means for positioning one only of said interponents in operative position comprises a cam shaft, a plurality of ordinarily arranged cams mounted progressively around said shaft, each cam operating the ordinarily related interponent, and means for rotating said shaft simultaneously with the operation of said shifting means.

11. In a calculating machine having an ordinarily arranged keyboard, an accumulator register ordinarily shiftable with respect to said keyboard, means for shifting said register, cyclically operable digitation means for differentially operating said accumulator register in accordance with a value set in said keyboard, a drive means for said digitation means, and an automatic multiplication mechanism including a control member operable to terminate operation of said digitation means, to initiate operation of said shifting means, and to reinitiate operation of said digitating means, a means for controlling operation of said control member which comprises a value cam associated with each order of the keyboard, means for setting said cams to represent various digital values, a slide associated with each order of the keyboard and movable to engage the value cam of the associated order, means operated by said drive means simultaneously with operation of said digitation means for moving one of said slides a predetermined increment upon each cycle of operation of said digitating means, means for sequentially determining the slide to be so moved, and means operated upon engagement of the operated one of said slides with the value cam of that order for operating said multiplication control member.

12. The apparatus of claim 11 comprising also means operated by said multiplication control member to operate the sequential determining means to disconnect the drive means and the operated one of said slides and to connect said drive means to the slide in the adjacent order of the keyboard.

13. The apparatus of claim 11 including also a means for blocking operation of said slides in all orders of which a "0" stands in the keyboard.

14. The apparatus of claim 11 including also a means for retaining said slide in an inoperative position in all orders in which no key has been operated and means operated by said shifting means to disconnect the drive means and the operated one of said slides and to connect said drive means to the slide in the adjacent order of the keyboard.

15. In a calculating machine having an ordinarily ar-

ranged register, an ordinarily arranged selection mechanism, a reversible digitation mechanism operable to enter a value set in the selection mechanism into said register additively or subtractively, a cyclically operable drive means for such digitation mechanism, means for shifting the relative ordinal position of the register and the digitation mechanism, an automatic multiplication mechanism including means for conditioning the digitation mechanism for additive or subtractive operation, and a shift control member operable to terminate operation of the digitation mechanism in one relative ordinal position, to operate the shifting means, and thereafter reinitiate a continuous series of operations of the digitation mechanism in another relative ordinal position, the improvement which comprises ordinarily arranged multiplier storage members positionable to represent the various digital values, means for positioning the storage members, ordinarily arranged auxiliary members associated with the orders of the multiplier storage members, each movable differentially to sense the value standing in the ordinarily related multiplier storage member, means driven by said drive means for moving said auxiliary members a predetermined incremental amount with each cycle of machine operation, ordinarily arranged interponents normally positioned out of engaging position to connect said auxiliary members to said means for moving said auxiliary members, means operated by said register shifting means for positioning only one of said interponents in operative position at a time, and means operated upon the engagement of the operated one of said auxiliary members with the ordinarily related multiplier storage member for operating said shift control member.

16. In a cyclically operated calculating machine having an ordinarily arranged selection mechanism, a register shiftable with respect to said selection mechanism, digitation means operative to enter a value set in said selection mechanism into said register, means for shifting said register, and a multiplier control member operative to terminate operation of the digitation mechanism in one ordinal position of the register, operate the shifting mechanism and initiate a continuous series of digitation operations in the adjusted ordinal position, the combination which comprises ordinarily arranged multiplier value indexing members associated with the orders of the selection mechanism, means for positioning said multiplier value indexing members in positions representative of the various digital values, a plurality of ordinarily arranged sensing members each associated with a selected order of the multiplier value indexing members and operative to determine the value position of the related multiplier indexing member, and means operated by the sensing members in sequence for controlling operation of the multiplier control member.

17. In a calculating machine having a value indexing means including a keyboard of ordinarily arranged depressible keys, means for holding a depressed key in its depressed position, a register shiftable with respect to said keyboard, a cyclically operable computing means for entering a value determined by said value indexing means into said register, and means for shifting said register, the combination which comprises a plurality of ordinarily arranged movable members each associated with a selected order of said keyboard, means for moving a selected one of said members a predetermined amount with each cycle of machine operation in a direction to engage a depressed key of the ordinarily associated order, means for sequentially selecting the member to be so moved, and means operated upon the engagement of the member with a depressed key for operating the shifting means and the selecting means.

18. In a calculating machine having a keyboard containing ordinarily arranged and manually operable keys, a register shiftable with respect to said keyboard, means for shifting said register, and a cyclically operable com-

puting means for entering a value determined by said keyboard into said register, the combination which comprises a plurality of ordinarily arranged movable members associated with selected orders of said keyboard, means for moving said members a predetermined amount with each cycle of machine operation in a direction to engage an operated key of the corresponding order, means operated by the movement of a movable member to a position determined by the operated key for operating the shifting means, and means for connecting said members to said moving means in a predetermined ordinal sequence.

19. In a cyclically operable calculating machine having a keyboard containing ordinarily arranged depressible keys, a register shiftable with respect to said keyboard, means for shifting said register, a digitation means operable to differentially operate said register in accordance with a value set in said keyboard, and a cyclically operable drive means, the combination which comprises a plurality of ordinarily arranged movable members associated with selected orders of said keyboard, means operated by said drive means for differentially moving said members in a direction to sense a depressed key of the same order, ordinal interponents for operatively connecting said members to said moving means, means operated upon the movement of a member to a position determined by a depressed key for operating the shifting means, and means operated by said shifting means for sequentially selecting one only of said interponents for operation to connect its respective member to said moving means.

20. In a cyclically operable calculator having a keyboard containing ordinarily arranged operable keys, a register shiftable with respect to said keyboard, means for shifting said register, and a cyclically operable digitation means to differentially operate said register in accordance with values set in the keyboard, the combination which comprises sensing members each respectively associated with a selected order of the keyboard and movable to sense which key is operated in its order, feed means for moving said members a predetermined increment with each cycle of operation of said digitation means, means for sequentially connecting one of said members to said feed means, means operated upon the sensing by a connected one of said members of the operated key in its order for terminating operation of said digitation means and initiating a cycle of operation of said shifting means, and means for blocking operation of said members in all orders in which no key has been operated.

21. In a calculator having an ordinarily arranged differentially positionable selection means, an ordinarily arranged accumulator, a cyclically operable digitation means for entering a value determined by said selection means into the accumulator, and means for shifting said accumulator with respect to said selection means, the combination which comprises a plurality of ordinarily arranged value sensing means movable to sense the position of the ordinarily related differentially positionable selection means, power driven feed means for moving said value sensing means predetermined increments of motion with each cycle of operation of said digitation means; ordinal interponents positionable to connect said drive means to the ordinarily related value sensing means, means for positioning one only of said interponents in operative position at a time, and means operated by the sensing means for operating said shifting means and thereafter operating said positioning means to move the previously operable interponent into inoperative position and position another interponent in operative position.

22. In a calculating machine having an ordinarily arranged keyboard, an accumulator register ordinarily shiftable with respect to said keyboard, means for shifting said register, cyclically operable digitation means for differentially operating said accumulator register in ac-

cordance with a value set in said keyboard, a drive means for said digitation means, and an automatic multiplication mechanism including a control member operable to terminate operation of said digitation means, to initiate operation of said shifting means, and to reinitiate operation of said digitating means, a means for multiplying a factor set in said keyboard by itself which comprises a slide associated with each order of the keyboard and movable to sense which key of the associated order is depressed, means operated by said drive means simultaneously with the operation of said digitation means for moving one of said slides a predetermined increment upon each cycle of operation of said digitating means, means operated upon the sensing of the operated one of said slides of the depressed key of that order for operating said multiplication control member, and means operated by said multiplication control member to disconnect the drive means and the operated one of said slides and to connect said drive means to the slide in an adjacent order of the keyboard.

23. In a calculating machine having an ordinarily arranged register, an ordinarily arranged value entering mechanism operable to enter a value set therein into the register additively or subtractively, means for shifting the relative decimal position of the register and the value entering mechanism, a drive means, and means for selectively connecting said drive means to said value entering mechanism and said shifting means, the improvement which comprises a plurality of ordinarily arranged value sensing members associated with selected orders of the value entering mechanism, each such value sensing member being operative to be moved progressively by predetermined increments of motion to sense the value standing in the associated order of the value entering mechanism synchronously with operation of said value entering mechanism, means for sequentially connecting the respective value sensing members to said drive means, and means operated upon engagement of a connected one of said sensing members with the ordinarily related value entering mechanism to operate said shifting means and said connecting means.

24. In a calculating machine having an ordinarily arranged register, an ordinarily arranged selection mechanism, a reversible digitation mechanism operable to enter a value set in the selection mechanism into said register additively or subtractively, drive means for such digitation mechanism, means for shifting the relative ordinal position of the register and the digitation mechanism, an automatic multiplication mechanism including means for conditioning the digitation mechanism for additive or subtractive operation, and a shift control member operable to terminate operation of the digitation mechanism in one order, to operate the shifting means, and thereafter reinitiate a continuous series of operations of the digitation mechanisms in another order, the improvement which comprises ordinarily arranged auxiliary members associated with the orders of the selection mechanism, each adapted to be moved differentially to sense the value standing in the ordinarily related selection mechanism, means driven by said drive means for moving said auxiliary members a predetermined incremental amount with each cycle of machine operation, ordinarily arranged interponents normally positioned out of engaging position to connect said auxiliary members to said means for moving auxiliary members, means operated by said register shifting means for positioning only one of said interponents in operative position at a time, and means operated upon the engagement of the connected one of said auxiliary members with the ordinarily related selection mechanism for operating said shift control member.

25. In a cyclically operated calculating machine having a selection mechanism including a keyboard of ordinarily arranged depressible keys, a register shiftable with respect to said keyboard, digitation means operative to enter a value set in said selection mechanism into said

register, means for shifting said register, and a multiplier control member operative to terminate operation of the digitation means in one ordinal position of the register, operate the shifting mechanism and initiate a continuous series of operations of the digitation means in the adjacent ordinal position, the combination which comprises a plurality of ordinally arranged sensing members each associated with a selected order of the keyboard and operative to determine which key is depressed in the associated order, and means operated by the sensing members in sequence for controlling operation of the multiplier control member.

26. In a calculating machine having a selection mechanism including a keyboard of ordinally arranged depressible keys, a register shiftable with respect to said keyboard, a cyclically operable digitation means operative to enter a value set in said selection mechanism into said register, means for shifting said register, and a multiplier control member operative to terminate operation of the digitation means in one ordinal position of the register, to operate the shifting mechanism and initiate a continuous series of operations of the digitation means in an adjacent ordinal position, the combination which comprises a plurality of ordinally arranged sensing members each associated with a selected order of the keyboard and operable in determined increments, means controlled by the depression of a key for blocking operation of the co-ordinal sensing member in a position determined by the depressed key, means for moving said member an increment with each cycle of operation of said digitation means, means for selecting one only of said members in sequence for operation, and means operated upon the blocking of a sensing member for controlling operation of the multiplier control member.

27. In a calculating machine having a value indexing means including a plurality of ordinally arranged positionable value members for registering a multiplier value, means for positioning said positionable members to represent selected values, a register shiftable with respect to said value indexing means, a cyclically operable computing means for entering a value determined by said value indexing means into said register, and means for shifting said register, the combination which comprises a plurality of ordinally arranged movable sensing members associated with said positionable value members, means for moving a selected one of said sensing members a predetermined amount with each cycle of operation of said digitation means, means for sequentially selecting the sensing member to be moved, means for blocking movement of said sensing members in a position corresponding to the value represented by the ordinally associated positionable value member, and means operated upon the blocking of movement of a sensing member for operating the shifting means and disabling the computing means.

28. In a calculator having an ordinally arranged differentially positionable selection means including a plurality of ordinally arranged value indexing members, means for setting said indexing members to represent various digital values, an ordinally arranged accumulator, a cyclically operable digitation means for entering a value determined by said selection means into the accumulator, and means for shifting said accumulator with respect to said selection means, the combination which comprises a plurality of ordinally arranged value sensing means movable toward engagement with the ordinally related indexing members, power-driven feed means for moving said value sensing means predetermined increments of motion with each cycle of operation of said digitation means, a plurality of ordinally arranged interponents positionable to connect said feed means to the ordinally associated value sensing means, means for positioning one only of said interponents in operative position at a time, and means operated upon the blocking of movement of the sensing means by its engagement with the ordinally related indexing member for operating said

shifting means and thereafter operating said positioning means to move the previously operable interponent into inoperative position and position another interponent in operative position.

5 29. In a calculating machine having an ordinally arranged selection means including a plurality of ordinally arranged value indexing members operable to represent a multiplier value, an accumulator register ordinally shiftable with respect to said selection means, means for shifting said register, cyclically operable digitation means for differentially operating said accumulator register in accordance with a value set in said selection means, a drive means for said digitation means, and an automatic multiplication mechanism including a control member operable to terminate operation of said digitation means, to initiate operation of said shifting means, and to reinitiate operation of said digitating means in the shifted position of the register, a means for controlling operation of said control member which comprises a movable member associated with each order of the selection means, feed means operated by said drive means in an intermediate portion of each cycle of operation of said digitation means for moving one of said movable members a predetermined increment, means for blocking movement of said movable members in a position corresponding to the value represented by the co-ordinal value indexing member, yieldable means operated in a subsequent portion of each cycle of operation for operating said multiplication control member, and means operated by said feed means for blocking operation of said yieldable means.

10 30. In a cyclically operable calculator having an ordinally arranged keyboard, a register shiftable with respect to said keyboard, means for shifting said register, and a digitation means operable to differentially operate said register in accordance with values set in the keyboard, the combination which comprises a member associated with a selected order of the keyboard and movable to positions determined by a depressed key in that order, means for feeding said member a predetermined increment with each cycle of operation of said digitation means, and means operated upon the engagement of said member with a depressed key for terminating operation of said digitating means and initiating a cycle of operation of said shifting means.

15 31. In a cyclically operable calculator having a keyboard containing ordinally arranged operable keys, a register shiftable with respect to said keyboard, means for shifting said register, and a cyclically operable digitation means to differentially operate said register in accordance with values set in the keyboard, the combination which comprises members each respectively associated with selected orders of the keyboard and movable into engagement with an operated key in the associated order, feed means for moving said members a predetermined increment with each cycle of operation of said digitation means, means for sequentially connecting said members to said feed means, means operated upon the engagement of a moving member with an operated key for terminating operation of said digitating means and initiating a cycle of operation of said shifting means, and means operated by said shifting means for operating said connecting means to disconnect the previously connected member and to connect another member to said feed means.

20 32. In a cyclically operated calculated machine having a selection mechanism including a keyboard of ordinally arranged depressible keys, a register shiftable with respect to said selection mechanism, digitation means operative to enter a value set in said selection mechanism into said register, means for shifting said register, and a multiplier control member operative to terminate operation of the digitation means in one ordinal position of the register, operate the shifting mechanism and initiate a continuous series of operations of the digitation means in the shifted position of said register, the combination which

comprises a plurality of ordinally arranged sensing members each associated with a selected order of the keyboard and operative in incremental steps to engage whichever key is depressed in the associated order, means for moving said members an increment with each cycle of operation of said digitation means, means for selecting one only of said members in sequence for operation, and means operated by a sensing member engaging its depressed key for controlling operation of the multiplier control member.

33. In a calculating machine having an ordinally arranged register, an ordinally arranged value entering mechanism operable to enter a value set therein into the register additively or subtractively, means for shifting the relative ordinal position of the register and the value entering mechanism, the improvement which comprises a plurality of ordinally arranged multiplier indexing members, ordinally arranged value sensing members cooperative with said multiplier indexing members, such value sensing members being operative to be moved progressively by predetermined increments of motion to sense the values standing in the coordinal multiplier indexing member, drive means for progressively moving said value sensing members, means for connecting successive ones of the value sensing members to said drive means for operation, and means operated by an operated one of said sensing members when sensing the value standing in the coordinal multiplier indexing member to operate said shifting means.

34. In a calculating machine having an ordinally arranged register, an ordinally arranged value entering mechanism operable to enter a value set therein into the register, means for adjusting the relative ordinal positions of the register and the value entering mechanism, and a multiplier control member operative to terminate operation of the value entering mechanism, operate the adjusting means to adjust the relative ordinal positions of the register and the value entering mechanism, and initiate a continuous series of operation of the value entering mechanism in the adjusted relative position, the improvement which comprises a plurality of ordinally arranged multiplier indexing members, a plurality of value sensing members coordinally arranged with said multiplier indexing members and each operative to sense the values represented in the coordinal multiplier indexing member, means operated by an operated one of said sensing members for operating said multiplier control member, and means for sequentially operating successive ones of said value sensing members.

35. In a cyclically operated calculating machine having a selection mechanism including a keyboard of ordinally arranged depressible keys, a register shiftable with re-

spect to said keyboard, digitation means operative to enter a value set in said selection mechanism into said register, means for shifting the relative ordinal positions of said register and said digitation means, and a multiplier control member operative to terminate operation of the digitation means in one relative position of the register and digitation means, operate the shifting mechanism and initiate a continuous series of operations of the digitation means in the adjacent relative position, the combination which comprises a plurality of ordinally arranged sensing members each associated with a selected order of the keyboard and operative to determine which key is depressed in the associated order, and means operated by the sensing members in sequence for controlling operation of the multiplier control member.

36. In a calculator having an ordinally arranged differentially positionable selection means, an ordinally arranged accumulator, a cyclically operable digitation means for entering a value determined by said selection means into the accumulator, and means for shifting the relative ordinal positions of said accumulator and said selection means, the combination which comprises a plurality of ordinally arranged value sensing means each movable to sense the position of the ordinally related differentially positionable selection means, ordinal interponents positionable to operate the ordinally related value sensing means, means for positioning one only of said interponents in operative position at a time, and means operated by the sensing means for operating said shifting means and thereafter operating said positioning means to move the previously operable interponent into inoperative position and position another interponent in operative position.
